AUTOMATIC BAG TOP FORMING AND SEWING APPARATUS

Frank L. Hopkins and Richard H. Ayres, Minneapolis, Minn., assignors to Bemis Bro. Bag Company, Minneapolis, Minn., a corporation of Missouri

Filed Nov. 2, 1961, Ser. No. 149,773
35 Claims. (Cl. 53—139)

This invention relates to new and novel apparatus for automatically shaping a bag top of a filled bag and providing a sewed closure after the bag top has been shaped. More particularly, this invention relates to apparatus for automatically conveying a filled bag from a filling machine, forming and positioning a bag top for sewing, and passing the formed bag top through a sewing machine, all without the aid of an operator.

To increase production in providing sewed bag top closures with the minimum of manual operations in shaping and positioning a bag top of a filled bag, particularly when the bag top is to be provided with a sewed tape closure, the art has been faced with the problem of providing mechanism that would automatically form a gusseted bag top and properly align the bag top in a level condition to have the sewed tape closure provided thereon. Further, with apparatus of the prior art it has not been possible to properly form and align a bag top for sewing operations as the bag is moved along the conveyer at the required speed for high speed operations. In order to overcome problems of the aforementioned nature, this invention has been made.

In is an object of this invention to provide apparatus for automatically shaping a bag top preparatory to forming a bag top closure and then sewing the bag top as the bag is being continuously advanced on a conveyer. A further object of this invention is to provide new and novel apparatus which is readily useable with various types of filling equipment for automatically shaping a bag top and providing the bag with the bag top closure. It is a still further object of this invention to provide new and novel apparatus for receiving a filled bag from the scale type filling apparatus and moving the filled bag through a bag top forming operation and thence advancing the formed bag top through a bag top sewing operation without the aid of an operator. Still another object of this invention is to provide new and novel apparatus for forming a bag top and providing a bag top closure that may be tape over sewing, tape under sewing, or sewing without tape.

Still another object of this invention is to provide in bag top forming and sewing apparatus, a new and novel V-shaped conveyer assembly which may be adjusted for maintaining the tops of various runs of different height bags at a given height, and properly positioning the bag top for a forming and sewing operation.

A still further object of this invention is to provide in automatic bag top forming and sewing apparatus, a new and novel assembly for automatically forming gussets in a filled bag and closing the bag top as the bag is being continuously advanced in a given direction. Still another object of this invention is to provide in automatic bag top forming and sewing apparatus, a new and novel gusset forming assembly that will first shape a bag top to have a rectangular plan configuration and thence close the bag top in a manner to form gussets thereon. Still another object of this invention is to provide in the aforementioned type apparatus a gusset forming assembly that will at least in part move an individual bag to a more nearly vertical condition as the gussets are being formed.

Still another object of this invention is to provide a new and novel bag top leveling and holding assembly for forcing the upper edges of the bag top to a predetermined

2

elevation and level condition and thence retain the bag top in the leveled condition as the bag is being continuously advanced relative to said assembly. A still further object of this invention is to provide a bag top leveler and holding assembly for automatically leveling the bag top to the proper elevation to have a sewed tape closure provided thereon as the bag is being advanced by suitable supporting mechanism.

Still another object of this invention is to provide in bag top forming and sewing apparatus having a conveyer for supportedly moving a bag, a new and novel bag top forming assembly that is operable for forming a gusseted bag top on one bag and a new and novel second assembly that at the same time automatically levels the bag top of a second bag and retains it in a leveled condition so as to be properly positioned for sewing operation independent of the operation of the gusset forming assembly.

Still another object of this invention is to provide apparatus for automatically carrying out the aforementioned objectives at high speeds. Another object of this invention is to provide a mechanism for automatically shaping bag top for forming a bag top closure on flat tube bags.

Other and further objects are those inherent in the invention herein illustrated, described and claimed and will be apparent as the description proceeds.

To the accomplishment of the foregoing and related ends, this invention then comprises features herein after fully described and particularly pointed out in the claims, the description setting forth in detail certain illustrative embodiments of various ways in which the principles of this invention may be employed.

The invention is illustrated by reference to the drawings in which the same numerals refer to corresponding parts and in which:

FIGURE 1 is a front side elevational view of the apparatus of this invention shown in conjunction with bag scaling and filling apparatus;

FIGURE 2 is a plan view of the apparatus of this invention;

FIGURE 3 is a fragmentary vertical cross sectional view taken along the line and in the direction of the arrows 3—3 of FIGURE 17 to more clearly illustrate the adjustable mounting feature of the side belt sub-assemblies and the mounting of the photo relay light emitting and receiving members;

FIGURE 4 is a fragmentary, somewhat perspective view of the gusset forming assembly and swinging guide assembly; said view showing the gusset formers in a datum position;

FIGURE 5 is a fragmentary, somewhat perspective view of the structure of FIGURE 4 in a position just prior to the time that the gusset formers are removed from the shaped bag top, and also illustrating the bag top creasing assembly.

FIGURE 6 is a fragmentary view, part in cross section, generally taken along the line and in the direction of the arrow 6—6 of FIGURE 2 to more clearly illustrate the structure for operating the gusset formers between the datum position and the position in which the gussets have been formed, said view showing the gusset formers in the position in which the gussets have been formed, and the gusset former assembly intermediate its uppermost and lowermost elevated positions;

FIGURE 7 is a vertical back end view of the mechanism of FIGURE 6, said view being taken along the line and in the direction of the arrows 7—7 of FIGURE 6 and showing part of the elements of FIGURE 6 in cross section. Portions of gusset former operating structure on the back side of the gusset former assembly are not illustrated;

FIGURE 8 is a plan view of the rear end portion of the mechanism illustrated in FIGURE 7, said view being gen-

erally taken along the line and in the direction of the arrows 8-8 of FIGURE 7 to illustrate the structure for moving the inside gusset formers between a transverse spread apart position, and a position closely adjacent one another and the mechanism for adjustably longitudinally positioning one set of gusset formers relative to the other set;

FIGURE 9 is a vertical side view taken along the line and looking in the direction of the arrows 9-9 of FIGURE 8 to more clearly show the mounting of one set of gusset formers and the structure for transversely spreading the inside formers;

FIGURE 10 is a transverse cross sectional view taken along the line and looking in the direction of the arrows 10-10 of FIGURE 11 to illustrate the swinging guide assembly;

FIGURE 11 is a fragmentary longitudinal cross sectional view generally taken along the line and looking in the direction of the arrows 11-11 of FIGURE 10 to illustrate the structures for moving the swinging guide assembly between a transverse spread apart condition and a position closely adjacent one another, and to show some of the structure for operating the gusset former cams;

FIGURE 12 is a horizontal view of the bag top creasing assembly, said view being generally taken along the line and in a direction of the arrows 12-12 of FIGURE 5 and showing portions of the intermeshing drive sprockets broken away to more clearly illustrate other portions of said assembly;

FIGURE 13 is a horizontal view of the bag top holding subassembly, said view (part in cross section) being generally taken along the line and looking in a direction of the arrows 13-13 of FIGURE 14;

FIGURE 14 is a fragmentary vertical side view of the bag top leveler holding assembly and the sewing machine;

FIGURE 15 is an enlarged cross sectional end view of the bag top leveler and holding assembly, said view being generally taken along the line and in the direction of the arrows 15-15 of FIGURE 13;

FIGURE 16 is an enlarged fragmentary top view of the single revolution clutch and the drive mechanism of the carriage control arm, said view in part shown in cross section, and being generally taken along the line and looking in the direction of the arrows 16-16 of FIGURE 17;

FIGURE 17 is a back side vertical elevational view of the apparatus of this invention, said view showing portions of the apparatus broken away;

FIGURES 18 and 19 together show a schematic diagram of the electric and pneumatic components and circuitry for the apparatus of this invention, said view also diagrammatically illustrating some portions of the structure which they control;

FIGURE 20 is a fragmentary perspective view of the bag top and gusset formers, said view illustrating the position of the gusset formers upon having shaped the bag top to be of rectangular configuration; and

FIGURE 21 is a horizontal view through the gusset formers at an elevation just above the top of the bag, said view illustrating the relative positions of the gusset formers just after they have completed the formation of the gussets.

The apparatus of this invention is to be used for providing bag top closures, either tape bound sewed bag top closures or plain sewed bag top closures on multiwall or single wall paper bags of the type that are nearly self-supporting in an upright opened condition, and in particular with bags of sizes to hold 25, 50 and 100 pound charges.

Now referring in particular to FIGURES 1, 2 and 17, there is illustrated a front side view, a plan view, and a back side view respectively of the automatic bag top former and filling apparatus, generally designated 10, of this invention. The machine 10 has been invented to be used in conjunction with an automatic bag scale and filling apparatus, for example with apparatus 11 as illustrated in FIGURE 1. The apparatus 11 will not be further

described other than to mention that it is of the variety on which an empty bag is manually positioned on the hopper spout 12 and thereafter releasably held on the spout by jaws 13 which are located on either side of the spout, there being switch mechanism for controlling the operation of the apparatus 11. Once the empty bag has been clamped to the spout of machine 11, it automatically weighs the desired charge to be filled in the bag 15 and drops the filled bag on the back end of the conveyor assembly 20 of the automatic bag top former and sewing machine 10.

Although the scale and filling machine 11 illustrated is the type which bags are manually positioned on hopper spout, it is to be understood that the automatic bag top former sewing apparatus 10 can equally as well be used in conjunction with an Automatic Bag Feeding Machine such as disclosed in the copending application of Jack D. Helm and Frank L. Hopkins, Ser. No. 806,955, now Patent No. 3,050,918, that picks up an unopened bag from a bag magazine, next opens and positions the opened bag on a hopper spout assembly, thence discharges a weighed charge into the bag and finally after carrying the bag to a position above a V-trough conveyor assembly drops the filled bag into said conveyor assembly. The aforementioned application of Jack D. Helm and Frank L. Hopkins is assigned to the same assignee of this application. If the automatic bag top former and filling apparatus of this invention is used in conjunction with a machine such as disclosed by the aforementioned application of Hopkins et al., the bag pickup, opening, filling, bag top forming, and sewing operations are completely automatic and therefore preferable over the use of the combination of the machine of this invention and the automatic bag scale and filling machine 11 illustrated in FIGURE 1.

The automatic bag top former and sewing machine 10 of this invention includes a frame generally designated 16, a V-trough conveyor assembly generally designated 20 mounted on said frame, and extending the length thereof, a side belt conveyor assembly generally designated 21 that is mounted above and extends substantially the length of the conveyor assembly 20, a gusset former assembly generally designated 22 mounted on the upper back end portion of the frame, a swinging guide assembly generally designated 23 mounted adjacent the gusset former assembly, a bag top creasing assembly generally designated 24 located forwardly of the swinging guide assembly, a bag top leveling and holding assembly generally designated 25 located forwardly of the bag top creasing assembly, a sewing machine assembly generally designated 26 located at the front end of the machine, drive mechanism generally designated 27 for driving each of the aforementioned assemblies, and control mechanism generally designated 28 for controlling the operation of the aforementioned assemblies. For purposes of facilitating the description of the machine 10, the end of the conveyor assembly 20 beneath the automatic bag scale and sewing machine 11 is considered the back end of the machine while the end beneath the sewing machine assembly 26 is referred to as the front end of the machine. The direction of movement of the bags on the conveyor assembly 20 is considered the longitudinal direction while the direction perpendicular to said longitudinal direction will be referred to as a transverse direction.

Frame.—The frame 16 includes a pair of transversely spaced front end uprights 30, each of which has lower ends thereof secured to the respective longitudinally base member 31 by a bracket 32; and a pair of transversely spaced back end uprights 33 secured to the respective opposite ends of said base members. Parallel longitudinal channel irons 36 are secured at their end positions to the top end portion of the respective upright while an intermediate longitudinal channel iron 37 is provided on either side and secured at its opposite ends to the adjacent upright. On either transverse side of the machine 10, a vertical brace 38 at one end is secured

to an intermediate portion of a channel iron 37 and at the opposite end to a channel iron 36. Spaced rearwardly of brace 38 and on the back side of the machine is a vertical brace 29 that likewise is secured to the adjacent members 36, 37.

As may be noted in FIGURE 2, a back end cross brace 39 at either end is welded to the adjacent top brace 36 and upright 33 while spaced, parallel, intermediate cross braces 40, 50 and 53 are welded to intermediate portions of the respective channel irons 36. Welded to braces 50, 53 and the channel irons 36 is a horizontal plate 114. A front end cross brace 41 is secured at either end to a juncture of upright 30 with top brace 36, there being a horizontal angle iron 35 located beneath brace 36 and secured to the uprights 30 and a second angle iron 42 at the same elevation welded to a vertical brace 38.

A longitudinally extending vertical plate 52 is bolted to adjacent portions of the front side channel iron 37 and uprights 30 and 31 while a vertical plate 91 of relatively short longitudinal length is welded to adjacent portions of the back side upright 33, brace 37 and lower longitudinal brace 99; brace 99 extending between and being welded to uprights 30 and 33. A forward vertical plate 92 is likewise welded to channel iron 37, upright 33 and brace 99.

V-trough conveyor assembly.—The V-trough conveyor assembly 20 includes a generally rectangular shaped base 45 made up of a pair of longitudinal channel irons 45a and a pair of transverse channel irons 45b. Mounted at each corner of the base 45 is a pulley support 46 having a drum pulley 47 journaled thereon. A V-shaped roller mounting frame 48 is mounted to extend between the drum pulleys at either end of the base, said frame mounting a plurality of rollers for supporting the upper run of each of the transversely inclined belts 49, there being a belt extended over each of the pair of drums 47 on either transverse side of the base 45. A plurality of rollers 51 are mounted on the roller mounting frame 48 for supporting the lower run of the respective belts, the roller mounting frame being mounted on a plurality of brackets 52 which in turn are bolted to the respective channel irons 45a in longitudinal space relationship.

A longitudinally elongated bracket 55 is secured to each end of the channel irons 45a in depending relationship thereto, each bracket having an elongated slot 55a for slidably mounting a stud shaft 56 that is mounted on the outer end of the respective crank arm 57. The opposite end of each crank arm is keyed to one of the two transverse shafts 58, each shaft being journaled for rotation in a pair of plates 59 secured to the respective upright mounting bracket. The shafts 58 are located more closely adjacent one another than the stud shafts 56 at the opposite ends of the frame 45.

One end of the operator arm 60 is keyed to each of the shafts 58, there being operator arms only on the front side of the machine. The opposite end of each operator arm is clevised and has pivotally connected thereto an internally threaded sleeve 61.

Mounted on the front bottom brace 31 is a vertically extending plate 65 that journals shaft 66 having a hand wheel 69 keyed thereto. The inner end of the shaft 66 extends into a housing (not shown) mounted on the plate 65, the housing journaling for rotation a pair of short longitudinal shafts that have keyed thereto beveled gears that are driven by a beveled gear mounted on the inner end of the shaft 66 (said beveled gears and longitudinal shafts not shown). To the outer end of each longitudinal shaft there is secured one member of universal joints 75, the other member of each universal joint being bolted to the inner end of a longitudinal rod 76. Each longitudinal rod has a threaded outer end portion having threads that form a matching fit with the threads of the respective sleeve 61.

By turning the hand wheel 69 in one direction, both

of the rods 76 are rotated in the same direction. However, since the threads on the two rods as mounted on the machine are pitched in opposite directions, the sleeves 61 are simultaneously moved in opposite directions. 5 Assuming the hand wheel is turned to cause the sleeve to move inwardly towards one another, then the front operator arm 60 is caused to be rotated in the direction of the arrow 80 about the axis of shaft 58 which in turn rotates a front shaft 58 and the crank arms thereon in 10 the same direction. This results in the front stud bolts 10 being moved arcuately rearwardly and forwardly, and in sliding in the slots 55a forces the front end of the frame to be elevated. Likewise the back sleeve 61 in 15 moving toward the hand wheel results in the back end of the frame being elevated.

Side belt conveyor assembly.—The side belt conveyor assembly 21 includes two side belt conveyor sub-assemblies that are of the same construction other than they are oppositely faced, one sub-assembly being designated a left-hand conveyor belt sub-assembly 80 and the other being a right-hand conveyor belt sub-assembly 81 (see FIGURES 1, 3, 17 and 19). The subassemblies 80 and 81 are mounted on the frame in a manner such that they may be adjusted relative to one another to vary the transverse spacing therebetween, the sub-assemblies being located above the V-trough conveyor assembly and extending as shown in FIGURE 1.

Since basically the sub-assemblies 80 and 81 are of the same construction, the structure of the sub-assembly 81 and the mounting thereof will first be described. Referring in particular to FIGURE 3, it is to be noted that the sub-assembly 81 has a roller mounting sub-frame that includes a pair of longitudinally spaced, vertical blocks 84 (only one being shown). A longitudinally extending top reinforcing plate 85 is secured to the top portions of the blocks 84 while a second reinforcing plate 85 is secured to the bottom portions of the blocks. Bolted to the top reinforcing plate and extending transversely outwardly thereof is a roller mounting member 82. A lower mounting plate 83 is bolted to the lower plate 85, the plates 82 and 83 mounting a plurality of vertically elongated rollers 86 and 87.

To the mid-portion of each block 84 there is secured a block 88 that mounts an internally threaded sleeve 93, the threaded end portion of a transverse shaft 89 being located in each sleeve. The opposite end of each shaft 89 is journaled for rotation in an annular retainer 90 but is held against transverse movement therein. The front retainer 90 is mounted on the front plate 92 and extends 50 through an aperture therein formed, the rear retainer 90 being similarly mounted on the rear plate 91.

To simultaneously move each of the blocks 84 in the same transverse direction the same amount, a sprocket 95 is keyed to each of the shafts 89, the sprockets mounting 55 an endless chain 96. A hand crank 97 is keyed to the outer transverse end of the rear shaft 89 for rotating said shaft and thereby through chain 96 rotating the sprocket on the front shaft. The sub-assembly 80 includes structure mounted for transverse movement that is the same 60 described relative to the sub-assembly 81 other than that the retainers 90 of the sub-assembly 80 are mounted in the front side plate 52.

Referring in particular to FIGURES 1 and 2, further structure of the conveyor belt sub-assemblies 80 and 81 65 will be described with reference to the sub-assembly 80. The sub-assembly 80 includes a driven pulley shaft 100 that has keyed thereto in vertical spaced relation, large diameter sheaves 101. The upper and lower ends of the shaft 100 are journaled for rotation in the forward end 70 of the mounting plates 82 and 83 respectively. Likewise journaled for rotation in the back ends of the mounting plates 82 and 83 is a pulley shaft 102 that has keyed thereto in vertical spaced relation a plurality of large diameter sheaves 103. Each of the corresponding pulley sheaves 75 101 and 103 mounts an endless belt 104.

For each of the sub-assemblies 80 and 81, the outer run of the endless belts after passing over the pulley sheaves 101 extend rearwardly and transversely inwardly due to the provision of the grooved roller 87 located adjacent the rear upright 33, said rollers also retaining the belts in vertical spaced relationship. The belts then extend longitudinally rearwardly over the grooved rollers 87 located adjacent the upright 30 and then around the pulley sheaves 103. The rollers 87 are journaled for rotation in the outer transverse edge of the respective mounting plates 82 and 83. The belts in passing around the sheaves 103 extend in a forward direction in abutting engagement with the plurality of vertical rollers 86 which are journaled for rotation between the inner transverse edges of the mounting plates 82 and 83. Some rollers 86 are likewise grooved in order to retain the inner run in vertical spaced relationship. The rollers 86 are closely spaced in order to retain the inner runs of the belts in position to support the adjacent side wall of a bag as it is moved forwardly on the V-trough conveyer assembly. The inner runs next extend forwardly to adjacent the upright 30 to pass over rollers 87.

Since the rear portions of mounting plates 85 and members 82 and 83 of the sub-assemblies 80 and 81 rearwardly of uprights 33 are angled in opposing direction, a bag receiving throat 105 is formed, said throat converging in a longitudinally forward direction (see FIGURE 19) to facilitate the entry of a bag between the sub-assemblies 80 and 81 after it has been dropped by the automatic bag filling scale machine onto the rearward portion of the V-trough conveyer.

Gusset former assembly.—The gusset former assembly 22 includes a carriage 111 mounted for slidably longitudinal movement on a pair of parallel transversely spaced track rods 113 (see FIGURES 2, 4-9, 11 and 17). Each of the rods at one end is secured to the back cross brace 39 and at the opposite end to a transverse bar 116 which in turn is mounted on cross brace 53. As may be noted in FIGURE 2, there is provided bellows 115 on each end portion of each track rod, the one end of each bellows being secured to the cross brace 36 or the bar 116. The bellows are provided to keep foreign material off track rods, the opposite ends of said bellows being secured to flange portion of adjacent end of the respective carriage sleeve 112 for movement therewith.

In order to move the carriage in a longitudinal direction (in the direction of arrow 117 or arrow 118) on the aforementioned track rods there is provided a stud shaft 120 secured to the back transverse sleeve 112 (see FIGURES 2, 11 and 17). One end of the linkage arm 121 is pivotally mounted on the stud shaft 120 while the opposite end of said arm is pivotally connected to the upper end of the control arm 122. The lower end of the arm 122 is keyed to a shaft 123 that is journaled for rotation in the open top housing 124 which is secured to the back side vertical brace 38 and the intermediate longitudinal brace 37 (see FIGURES 16 and 17). In order to pivot the control arm 122 about the axis of the shaft 123, first in the direction of arrow 128 and then in the opposite direction, one end of an operator arm 129 is pivotally connected to the control arm intermediate the shaft 123 and the pivotal connection of the linkage 121 to the arm 122.

As may be noted in FIGURES 16 and 17 the one end of the operator arm 129 is secured to the intermediate portion of the control arm 122 by the pivotal connection 127. The opposite end of the control arm has elongated slot 130 through which bushing 126 extends, said bushing being mounted on the cam shaft 131 which is journaled for rotation in opposite vertical walls of housing 124. The cam shaft is located forwardly and upwardly of the shaft 123.

Keyed to the cam shaft is a cam 132, having a recessed endless cam track 132a. A cam follower 133 is mounted on the intermediate portion of the operator arm to bear against the cam track 132a. Since the radial distance of

various portions of the cam track to the axis of the shaft 131 varies, the operator arm 129 is caused to move in a longitudinal direction (arrow 117 or arrow 118) and thereby cause the control arm 122 to pivot about axis of shaft 123 and move the carriage in the same longitudinal direction.

Referring again to FIGURES 2 and 6, it is to be noted that the carriage 111 includes in addition to the sleeves 112, a transverse brace 135 that is secured at its opposite ends to one end portions of sleeves 112 and a second transverse brace 136 that at its opposite ends is secured to the opposite ends of the sleeves. Mounted inwardly of the sleeves and having opposite ends secured to the respective braces 135 and 136 are a pair of transversely spaced parallel mounting plates 137. An angle brace and horizontal plate 138 is bolted to the brace 136 to extend intermediate the aforementioned 138 mounting plates and be welded thereto; while a second angle (oppositely faced) and plates are bolted to brace 135.

Mounted on the carriage to depend therefrom and for limited vertical and longitudinal movement relative the carriage is the gusset former sub-assembly generally designated 140. The sub-assembly 140 includes a pair of transversely spaced longitudinally extending bars 141, each having an upwardly extending bracket 142 bolted thereto. The structure mounting the gusset former sub-assembly for movement includes a pair of transversely spaced linkage arms 144 that at the one ends are welded to a sleeve 147 that has the upper ends of the bracket 142 pivotally connected thereto by the pivot member 145. The opposite ends of the linkage arms 144 are welded to the sleeve 150. A second pair of transversely spaced linkage arms 148 which are mounted for movement parallel with linkage arms 144 are at their one ends pivotally connected to lower ends of the respective brackets 142 by pivot bolts 149 having appropriate spacers 154 thereon intermediate members 142 and 148. The opposite ends of the linkage arms 148 are pivotally connected at 152 to the lower end of the depending bracket 151. The upper ends of brackets 151 are welded to a block 153, each block 153 being welded to the respective mounting plate 137 adjacent the transverse brace 136. A transverse pivot shaft 146 is mounted in aforementioned blocks 153 and the mounting plates 137, said shaft rotatably mounting the sleeve 150.

In order to provide movement of the gusset former sub-assembly through the structure of the preceding paragraph, the lower end of an arm 156 is welded to the mid-portion of the sleeve 150. The outer clevised end of the piston rod 157 of the two way acting piston cylinder combination 160 is pivotally connected at 158 to the upper end of the arm 156. The cylinder 161 of the piston cylinder combination at its back end is pivotally connected to the bracket 163 by the pivot 162, the bracket 163 in turn being bolted to the bracket 164 that is welded to the transverse brace 138 of the carriage.

Referring now in particular to FIGURES 6, 7 and 8, it is to be noted that there is provided a front outside gusset former 166, inside gusset formers 167 and 168 respectively located on either transverse side of the former 166, a back outside gusset former 169, and inside gusset formers 170 and 171 respectively located on either transverse side of the former 169. The gusset formers 166-171 inclusive are located intermediate the longitudinal bars 141 and mounted for movement relative thereto. Basically the structure mounting the set of gusset formers 169-171 for movement is the same as that mounting the set of gusset formers 166-169 other than the exceptions noted hereinafter.

The upper end of the gusset former 169 is bolted to the outer end of an outwardly extending projection 175 of the hub 176 which is keyed to the central portion of the shaft 177 to rotate therewith, the opposite ends of the shaft being journaled for rotation in the respective slide member 178 that are adjustably slidably retained on a

bar 141. Keyed to the shaft 177 intermediate the front bar 141 and the hub 176 is a spur gear 179. A generally U-shaped clamp 180 is mounted on the shaft 177 intermediate the spur gear and the hub to retain the spur gear in a proper axial position on the shaft.

The spur gear 179 drivingly engages a spur gear 184 rotatably mounted on the shaft 185 which has its opposite end portions journaled for rotation in the respective slide member 178 forwardly of the shaft 177. A cam 186 is rotatably mounted on the shaft 185 for movement with the spur gear 184.

On the shaft 185 intermediate the cam 186 and the back bar 141 there is keyed a hub bracket generally designated 190. The bracket 190 has a pair of spaced outwardly projecting ears 191 for rotatably mounting the former hub 192, there being a pivot member 193 for pivotally retaining the former hub between the ears 191. The former hub has on one side projecting boss to which the cam follower 194 is rotatably secured to bear against the cam surface of the cam 186, and across from the boss there is an integrally formed radially projecting flange 192b which has a radial slot 192c formed therein. The former hub 192 also has a depending flange 192a to which the inside gusset former 170 is bolted, the former having a pair of elongated slots 170a to permit it being secured to the portion 192a in an adjusted longitudinal position.

The hub bracket has a second pair of spaced ears 196 located transversely between ears 191 and the back bar 141. The former hub 197 is pivotally secured between the ears 196 by a second pivot 193 and has a pair of radially projecting flanges 197a located to respectively underlay and overlay the flange 192b. A stud shaft 198 is mounted in the outer radial portions of flanges 197 to extend through the slot 192c, for oppositely rotating the hub former 197 when the hub former 192 rotates in one direction. A coil spring 196a having one end bear against the hub bracket and the opposite end connected to shaft resiliently urges the former hub 192 to rotate in a direction opposite arrow 784.

The outside former 166 is mounted on a shaft 201 and the inside formers 167, 168 are mounted on a shaft 200 by a structure corresponding to the structure mounting the formers 169, 170, 171, respectively on the shafts 185 and 177, other than it is oppositely faced in order that as the lower end of former 169 is moved in one longitudinal direction the lower end of former 166 will move in the opposite longitudinal direction and that when the lower ends of formers 170, 171 are moved in one longitudinal direction the lower ends of former 167, 168 will move in the opposite longitudinal direction. The end portions of the shaft 200 and 201 are journaled for rotation in respective forward end portion of bar 141 but the shafts 200 and 201 are not free to be adjusted in a longitudinal direction relative to the bars 141.

The back end portions of each bar 141 has an elongated longitudinally extending aperture 206 through which a bolt for securing a slide block 178 on the outer transverse side of the bar 141 and a slide member 181 on the opposite side of the bar. Each slide block 178 has outwardly projecting flange portions that bear against the horizontal surfaces of the respective bar 141. Upon loosening the bolts 208 the slide bars and slide members no longer clampingly engage the bars 141 and thereafter the shafts 177 and 185 together with the structure mounted thereon may be moved longitudinally relative to the shafts 200 and 201. This adjustment is provided in order to permit the gusset former assembly being adjusted for use with bags of different size bag top openings.

In order to facilitate the adjustment of the slide members on the bars 141 there is provided the adjustment mechanism generally designated 214 (see FIGURES 5-8). The adjusting mechanism includes a transverse tab 215 mounted on the back end portion of each bar 141. Rods 216 and 217 are journaled for rotation in

the respective tab but held therein against longitudinal movement, each of the rods 216, 217 extending in a longitudinally forward direction and having a front threaded end portion extending into the internally threaded tab 218 that is fixedly secured to the respective slide member 173. On the back end portions of each of the rods 216, 217 there is keyed a chain sprocket 219, there being a chain 220 mounted on said sprockets for simultaneously rotating the sprockets in the same direction. The back end of the rod 217 has an end portion 217a to have a hand crank mounted thereon for rotating the rod 217.

After loosening the bolts 208 so that the slide member and slide block respectively form a non-clamping fit with the respective bar 114 and mounting the crank on the portion 217a, upon turning the hand crank both of the rods 216, 217 are simultaneously turned in the same direction. For example, if the rods are rotated in a proper direction to move the slide members in the direction of the arrow 117 (see FIGURE 6) then the gusset formers 169, 170 and 171 would likewise be moved in the same direction away from the gusset formers 166, 167 and 168. After moving the gusset formers 169-171 the desired amount, the bolts 208 are again tightened so that the slide member and blocks form a clamping fit with the respective bars 141. In making the aforementioned adjustments, it will also be necessary to make adjustment of tie rods that will be described hereinafter. After the adjustments described in this paragraph have been made, then the gusset former assembly is ready to be used with bags that have bag tops that in an open condition have a larger cross sectional area than the bags for which it was previously set.

Spacer rods 205 at either end are secured respectively to the front and back ends of the bars 141, and a bar 225 at its opposite ends is secured to the front top portions of the slide blocks 178 for holding the bars 141 and slide blocks respectively in proper spaced relationship. The bar 225 minimizes the bending that would otherwise occur when longitudinally repositioning the slide members 178 on the bars 141.

The structure for mounting the gusset formers 166-171 and the structure for adjustably positioning gusset formers 166-168 and 169-171 relative to one another having been described, the structure for imparting movement to the respective shafts to which the gusset formers are mounted will now be set forth. The gusset former drive mechanism includes a tie arm 230 that at one end is keyed on the back side end portion of the shaft 201 transversely outwardly from the bar 141. The opposite end of the arm 230 has one end of the drive rod 231 connected thereto by a pivot member 232 in spaced relation to pivot member 234 which pivotally connects one end of the tie rod 233 to arm 230. The tie rod 233 extends rearwardly and downwardly to cross a horizontal plane passed through the axes of rotation of the shafts 201 and 177 and at its opposite ends is pivotally connected at 236 to the outer end of the arm 235. The opposite end of the arm 235 is keyed to the outer end of the shaft 177. Thus, the arm 230 causes the shaft 201 to rotate in one direction while the shaft 177 is rotated in the opposite direction the same angular amount.

The opposite end of the drive rod 231 is pivotally connected at 241 to the lower end of the drive arm 240. The hub portion of the drive arm is rotatably retained on the pivot 242 that is mounted on the back side mounting plate 137. Formed integral with the hub portion is an operator arm 243 that extends outwardly at an angle to the drive arm. The opposite end of the operator arm pivotally mounts cam follower 244 that is positioned to follow the cam surface of the cam 246 that is keyed to the cam shaft 247 (see FIGURE 7). The cam shaft at its opposite end portions is journaled for rotation in the respective mounting plate 137 while the pivot 242 is located at a lower elevation than the cam shaft.

In order to rotate the cam shaft 247 there is keyed

thereto a chain sprocket 248 located intermediate the carriage and the back top brace 36, there being a chain 249 extended partially around the chain sprocket and at one end fixedly secured to the back top cross brace 39 at 249a, and at the opposite end fixedly secured at 253 to the plate 305 dependently secured to bar 116 (see FIGURES 2, 3, 11 and 17). A pair of longitudinally spaced sprockets 251 are mounted on the back carriage sleeve 112 at a lower elevation than shaft 247, one sprocket being located on either side of the shaft 247. The sprockets are positioned to engage the chain for holding it in driving relation with the chain sprocket 248 as the carriage is moved in relation to the chain. By moving the carriage in one direction, for example opposite arrow 117, the sprocket 248 is caused to rotate in the direction of arrow 15 254 (see FIGURES 11 and 17) to rotate shaft 247.

Also keyed to the shaft 247 but intermediate the front side mounting plate 137 and the adjacent top brace is a cam generally designated 260 (see FIGURE 6). The cam 260 includes a cam hub 261 keyed to the shaft 247 to rotate therewith, the hub being provided with elongated arcuate slots 263. Bolted at 264 to the hub is a cam plate 262, the angular position of the cam plate relative to the hub and shaft 247 being adjustable by loosening the bolts 264 that extend through the slots 263 and rotating the cam plate relative to the hub. After the cam plate is rotated to the desired position, the bolts 264 are again tightened. It is to be mentioned that cam 246 is of the same construction as cam 260 but oppositely faced.

The outer peripheral surface of the cam plate 262 bears against cam follower 268 that is rotatably mounted on the outer end of the operator arm 269. The inner end of the operator arm is formed integral with the hub portion of the drive arm 271, said hub portion being rotatably retained on pivot member 270 that is mounted on the front side plate 137. A coil spring 278 at one end is secured to the intermediate portion of the drive arm 271 at 279 and the opposite end is secured to the mounting plate at 280 at a position upwardly and forwardly of the coil spring mount 279. The aforementioned coil spring resiliently urges the drive arm to rotate about the axis of the shaft 270 in the direction of arrow 281 to retain the cam follower 268 in engagement with the cam plate 262, it being noted that a second coil spring (not shown) is likewise mounted on the back side plate and drive arm 240.

One end of the drive rod 273 is pivotally connected to the outer end of the drive arm 271 by a pivot member 272, the opposite end of the drive rod being pivotally connected at 275 to the outer end portion of the arm 274. The opposite end of the arm 274 is keyed to the end portion of shaft 200 that extends transversely outwardly from the front side bar 141.

Rearwardly of the pivot 275 and radially outwardly of the shaft 200 there is provided a pivot member 283 that pivotally connects one end of the tie rod 284 to the arm 274, the opposite end of the tie rod being pivotally connected at 285 to outer end of the radial arm 286, said radial arm being keyed to shaft 185. The tie rod 284 and arms 274 and 286 are mounted to rotate shaft 185 in a direction opposite the rotation of the shaft 200.

It is to be mentioned that each of the drive rods 231, 273, and each of the tie rods 233, 284 are of a construction that they may be selectively adjusted in length. Thus, if the position of the gusset formers 169-171 is varied relative to the longitudinal position of the gusset formers 166-168 the length of each of the rods 231, 233, 273 and 284 are likewise adjusted to be of an appropriate length so that the gusset formers will function in a manner described hereinafter.

Swinging guide assembly.—Referring now in particular to FIGURES 2, 10 and 11 and also to FIGURES 4, 5 and 17, the swinging guide assembly generally designated 23 will now be described. The swinging guide

assembly includes six guide arms 290-295 inclusive, the guide arms 290, 291 and 292 being mounted on the back side of the machine and being longitudinally spaced relative to one another. The guide arm 293, 294, 295 likewise are mounted in the same longitudinal spaced relation; however, they are located on the front side of the machine (see FIGURE 4). Three horizontal arms 296 at their mid-portion are connected to lower end of the respective guide arm 290-292 inclusive by a pivot member 298. The inner end of each arm 296 has a generally vertically extending guide plate 297 secured thereto, the guide plates having lower horizontally extending flange 297a formed integral with the vertical portion thereof. Likewise, each of the guide arms 293-295 respectively have pivotally connected thereto by pivot member 298 a horizontal arm 299. Each horizontal arm 299 mounts a guide plate 300 at the end that is most closely adjacent the respective guide plates 297, the plates 300 being oppositely faced from plates 297.

The upper end of guide arm 290 is clamped on the back end portion of a longitudinally extending rod 302 to rotate therewith, the back end portion of the rod being journaled for rotation in one end portion of a plate 303. The opposite end of the plate is bolted to a depending bracket 304 that at its upper end portion is secured to the adjacent top brace 36. The opposite end portion of the rod 302 is journaled for rotation in the depending plate 305. Appropriate spacers 306 are mounted on the rod 302 to bear against the respective plate 303 and 305 to prevent longitudinal movement of the rod 302.

The upper end of the guide arm 291 is clamped on the guide arm tube 308 which in turn is rotatably mounted on the guide arm rod 302. The tube 308 is located intermediate the plates 303 and 305 and is retained in a given longitudinal position by spacer members 309 that are mounted on the rod 302. A shorter guide tube 310 is rotatably mounted on the guide tube 308, there being provided spacers 311 for holding the guide tube 310 in a given longitudinal position on tube 308. As may be noted in FIGURE 11, either end of the guide tube 308 extends in a direction axially away from the adjacent ends of the guide tubes 310 while the guide rod 302 is elongated to have either end portion extend axially outwardly from the adjacent end portions of the guide tube 308.

The guide arms 293, 294, and 295, other than being oppositely faced are mounted in a manner similar to the mounting of guide arms 290, 291 and 292, the upper end of the guide arm 295 being clamped to rod 314 which is journaled for rotation in a plate 317 that is bolted to the plate 318. Plate 318 is secured to the front top brace 36. The opposite end portion of the tube 314 is journaled for rotation in a plate 305 secured to bar 116. The upper end portion of the guide arm 294 is clamped to the guide tube 315 that is rotatably mounted on the guide rod 314, while the upper end of the guide arm 293 is clamped to the guide tube 316 that in turn is rotatably mounted on the guide tube 315.

In order to retain the vertical surfaces of the guide plates 297 in general vertical plane as the arms 296 are moved from an "out" position (shown in dotted lines in FIGURE 10) to an "in" position (shown in solid lines in the same figure), each of the arms 296 at the end opposite the respective guide plate is pivotally connected to one end of a control rod 327 by a pivot member 328. The opposite end of each control rod is rotatably mounted on a longitudinally extending rod 329, the end portion of the rod 329 being secured to plate 303 and plate 305 respectively. The horizontal spacing of rods 302 and 329 is the same as the spacing of pivot 298 and 328, while the distance from rod 329 to pivot 328 is the same as that from rod 302 to pivot 298.

The outer transverse ends of the horizontal arm 299 are each pivotally connected at 331 to the lower end of the respective control rod 330. The upper ends of the

control rods are rotatably mounted on the longitudinal rod 332, the end portions of the rod being mounted in plate 317 and plate 305 respectively. It is to be mentioned that each of the control rods 327 and 330 are of a construction to be selectively varied in longitudinal length to thereby properly position the guide plates 297, 330 relative to one another when said guide plates have been moved to the position most closely adjacent each other to have their horizontal flanges bear against a bag top side wall.

In order to operate the guide plates, for example, guide plates 297 from the dotted line position illustrated in FIGURE 10 to the solid line position of the same figure, there are provided plates 336, 337, and 338, each having an aperture at one end portion thereof for mounting the plates on the guide tubes 310, 308 and the guide rod 302 respectively to rotate the respective tubes and rod. An outer radial end portion of each of the aforementioned plates 336-338 is pivotally connected at 339 to one end of the respective linkage rod 340. The opposite ends of each of the three linkage rods 340 is pivotally connected at 342 to the outer end of one of the radial arms 343, 344 and 345 respectively, the other end of the arm 343 being mounted on the guide tube 316, the arm 344 being mounted on the guide tube 315 and the arm 345 being mounted on the guide rod 314. As a result of providing the aforementioned plates 336-338 and arms 343-345, when the plate 336 is pivoted to cause the guide arm 292 to rotate in one direction, the arm 343 causes the guide arm 293 to rotate in the opposite direction the same angular amount. Likewise, arm 344 rotates the guide arm 294 and the arm 345 rotates the arm 295.

In order to drive each of the plates 336-338 there are provided three elongated drive arms 351, each drive arm at its lower end being connected to the outer end of the respective plate by a pivot member 352 angularly spaced from the pivot 339. The upper end portion of each of the drive arms is enlarged and has an elongated rectangular slot 353 formed therein through which cam shaft 354 is extended, it being noted that the transverse width of the slot is substantially greater than the diameter of the cam shaft. On the upper end of each drive arm there is rotatably secured a cam follower 355 that rides the outer circumferential surface of the respective cam followers 356, 357 and 358. Each of the cams has a hub 356a, 357a, and 358a respectively that are keyed to the shaft 354 to rotate therewith, and an angular portion 356b, 357b, and 358b respectively that projects radially outwardly a greater distance from the hub than the remaining portion of the cam.

One end portion of the cam shaft 354 is journalled for rotation in an upright bracket 360, the bracket being bolted to the angle iron 40. The structure for rotatably supporting the opposite end of the cam shaft will be described hereinafter.

The hub portion of each of the cams is secured to the cam shaft so that the cams are angularly positioned relative to one another. Due to the configuration of the outer periphery of each respective cam and the angular mounting of the cams on the cam shaft, all of the guide arms are simultaneously moved inwardly to the solid line position illustrated in FIGURE 10 while first the guide arms 290 and 295 moved outwardly to the dotted line position of FIGURE 10; next the guide arms 291 and 294 are moved outwardly and then the guide arms 292 and 293 are moved outwardly. The cam 358 controls movement of the guide arms 290, 295 while the cam 357 controls the movement to the guide arms 291 and 294, and the cam 356 controls the movement of the guide arms 292 and 293. Each of the drive arms 351 at its lower end has one end of a coil spring 361 secured thereto, the opposite ends of the coil springs being secured to bars 362 which are secured to the casting 376 (see FIGURE 13). The aforementioned coil springs resiliently urge the respective drive arms in a downward direction to thereby

insure that cam followers are held in engagement with the respective cams 356-358.

Bag top creasing assembly.—Referring now in particular to FIGURES 4, 5 and 12-14 inclusive, the bag top creasing assembly 24 will now be described. For mounting the bag top creasing assembly there is welded to the channel iron 42 a depending plate 375. Welded to one transverse side of the plate to extend rearwardly thereof in a horizontal direction is the elongated casting 376, a sleeve 377 being welded in an intermediate cut-out portion of the casting for journaling the vertical shaft 378 (see FIGURE 13). An elongated vertical plate 381 is welded to the top of the casting to extend on either side of sleeve 377. A pair of transversely extending longitudinally spaced spacers 379 at one end are welded to the plate 381 for mounting the short elongated plate 383 parallel to plate 381 on the opposite side of the longitudinal axis L—L. A short horizontal plate 382 is welded to the bottom edge of the plate 383.

20 A horizontal plate 386 is mounted beneath the casting 376 while an oppositely faced plate 387 is mounted beneath plate 382, there being provided a pair of spacers 388 and bolts 389 for mounting the plates 386 and 387. Each of the plates 376, 386, 382 and 387 have elongated slots 390 formed in the rearward portions thereof and small blocks 391 mounted to extend across the slots. Each block has a non-threaded aperture through which a non-threaded portion of a bolt 393 is extended, the bolts each side of the longitudinal axis L—L mounting the respective end portions of a pulley shaft 394. By turning the bolts in the blocks, the longitudinal position of the pulley shaft may be varied due to the end portion of the bolts having threads that form a matching fit with threaded apertures in the shaft through which they are extended.

35 On the opposite side of the longitudinal axis L—L from the casting 376 a pair of vertically spaced lugs 395 are welded to the plate 375. A T-bracket 396 is welded to the vertical sleeve 398 which is pivotally mounted on a pivot shaft 397, said pivot shaft being mounted by the lugs 395. A shaft 399 is journalled for rotation in the vertical sleeve 400 to extend upwardly and downwardly therefrom, the sleeve 400 in turn being welded to the rear edge portion of the T bracket 396.

40 Welded to the circumferential portion of the sleeve 400 opposite the T-bracket is a tab 401 that has a slot elongated in a longitudinal direction through which the mid-portion of the bolt 402 is extended. A coil spring 404 is positioned on the bolt to have one end bear against the tab and the opposite end bear against a washer and nut 403 threaded on the outer transverse end of the bolt. The opposite end of the bolt is welded to the elongated plate 381. The coil spring acting against the tab resiliently urges the sleeve and the structure thereon to pivot about the pivot shaft 397 in a direction of the arrow 405, the elongated slot in the tab 401 permitting limited pivotal movement of the shaft 399 about the pivot axis of shaft 397.

45 A plurality of large diameter, vertically spaced sheaves 410 are keyed in vertical spaced relation on the portion of the shaft 399 that extends downwardly beneath the sleeve 400. Extended around each of the large sheaves except the lowermost one is a continuous belt 412, each of the belts 412 also being extended around a corresponding sheave 411 that is keyed on the shaft 394. Likewise, the shafts 378 and 394 on the opposite side of axis L—L mount the same number of large sheaves 410 and small sheaves 411 respectively beneath the casting 376, there being the same number of belts 412 extended around the sheaves beneath casting 376. As may be noted in FIGURE 12, a transverse spacing W between the adjacent belts as they pass over the sheaves 311 progressively decrease in a direction toward the shafts 378, 399, the purpose of mounting the belts so that the inner runs converge in a forward direction will be set forth herein-
50 after.

In order to drive the belts 412, a spur gear 413 is keyed to each of the shafts 378 and 399 in driving relationship with one another. A chain sprocket 414 is keyed on the end of the shaft 378 above the spur gear 413. The structure for driving the chain sprocket will be set forth hereinafter.

Bag top leveling assembly.—Referring now in particular to FIGURES 13, 14, and 15, the bag top leveling assembly 25 will now be described. The bag top leveling assembly includes a bag leveling sub-assembly generally designated 425 and a bag top holding sub-assembly 426. The bag top holding sub-assembly, which will first be described, includes a pair of transversely spaced elongated plates 430 and 431. A vertical plate 427 is welded to the cross brace 35 to depend therefrom, plate 427 having spaced horizontal tabs 428 to which the plates 430 and 431 respectively are bolted to be located on opposite sides of longitudinal axis L—L. Horizontal tabs 429 likewise are bolted to opposite end portions of plates 430, 431; tabs 429 being secured to the lower end of plate 375.

One end of a generally longitudinally extending feeler arm 433 is pivotally secured at 434 to the mid-portion of the mounting plate 430 to be located therebeneath. The feeler arm has an opposite end 433a bent inwardly to extend across the space between the plates 430 and 431 in position to abut against a bag top of a bag moving between said plates.

A micro switch 436 is secured to the mounting plate to depend therefrom, said switch having a push button 437 resiliently urged to an OFF position and located to abut against the mid-portion of the feeler arm to hold it in a datum position to be engaged and moved in the direction of arrow 438 to move the push button to an ON position by a bag being moved between the plates 430 and 431. The switch 436 includes resilient member (not shown) that urges the push button 437 to an OFF position and thereby the feeler arm to a datum position after the bag has advanced past said arm. A peg 439 is mounted on a longitudinally elongated bar 440 to limit the amount of movement the feeler arm in a direction opposite arrow 438.

The bar 440 is bolted to the underside of the plate 430 adjacent to the inner transverse edge thereof, while a corresponding bar 441 is mounted beneath plate 431 for movement toward and away from the bar 440. The structure mounting bar 441 includes a pair of longitudinally spaced short linkage members 442 each of which have one end pivotally retained in a recess formed in the bar 441 by a pivot 443. The opposite end of each of the linkages 442 is pivotally connected by a pivot member 445 to the outer end of one leg of a right angle linkage 446 and 447 respectively. Each of the right angle linkages has a hub portion that is pivotally mounted on a pivot member 448, the pivot member 448 being secured to the plate 431 to depend therefrom.

One end of a tie rod 431 that is adjustable in length, is pivotally connected at 452 to the outer end of the link of the second leg of linkage 447 while the opposite end of said tie rod is pivotally connected at 453 to an intermediate portion of the corresponding leg of the linkage 446. To the outer end of the last mentioned leg, the piston rod of a one way acting piston cylinder combination, generally designated 456, is pivotally connected at 457 while the far end of said combination is pivotally connected at 458 to an intermediate portion of the transverse bar 459. The inner end of the transverse bar is bolted to an intermediate portion of the mounting plate 431.

The piston cylinder combination upon having air under pressure applied thereto pivots the right angle linkage 446 in the direction of the arrow 460 about the pivot 448, the movement of the linkage 446 being limited by an adjustable stop 461 that is welded to the mounting plate 431. A coil spring 462 has one end secured to the

linkage 446 and an opposite end secured to the forward end portion of the mounting plate 431 for resiliently urging the linkage 446 to rotate in a direction opposite arrow 460 to return it to a datum position when no air under pressure is applied to cylinder 456.

Since the linkages 442 are pivotally mounted at either end to structure movable relative to the mounting plate 431, there are provided a pair of spring steel members 465 which are mounted in longitudinally spaced relationship. One end of each member 465 is bolted to the underside of the mounting plate 431 while the opposite ends of members 465 are bolted to the longitudinal bar 441. The aforementioned spring steel members resiliently retain the longitudinal bar 441 in predetermined transverse spaced relationship relative to the bar 440. In order to increase the aforementioned spacing, the aforementioned piston cylinder combination 456 is actuated to move the right angle linkage in a direction opposite the arrow 460, said combination upon being de-actuated results in the bar 441 moving back to the datum position (position of FIGURE 13) due to springs 465 and 462.

An endless belt 469 is extended around the lowermost sheaves 410 on the pulley shaft 399 and has an outer run that is extended over the small sheave 470 that is rotatably mounted on the outer end of the transverse bar 459 to depend therefrom. On the forward end of the mounting plate 431 a sheave 471 is journaled for rotation and mounted for limited adjustable longitudinal movement relative to said plate. The belt 469 is extended around the sheave 471 and has the inner run 469a thereof retained in the recess formed in the belt guide 472 which is mounted on the longitudinal bar 441. The belt guide is of a length to extend substantially the longitudinal distance intermediate the sheaves 471 and 410.

A second sheave 471 is likewise mounted on the forward end portion of the plate 430 to have an endless belt 473 extended therearound and around the lowermost sheaves 410 on the pulley shaft 378. The inner run 473a of belt 473 is located in a recess formed in the belt guide 474 which is secured to the longitudinal bar 430. Each of the belts 469 and 473 are of a thickness to be located more closely adjacent one another than the most adjacent vertical edge portion of the belt guides.

The bag top holding subassembly 426 having been described, the structure of the bag top level sub-assembly 425 will now be set forth (see FIGURES 14 and 15). The sub-assembly 425 includes a pair of transversely spaced longitudinally extending mounting plates 480, the one end of said plates being welded to the upper end of the upright bracket 481 which is mounted on the center portion of the cross-brace 35. The opposite ends of the mounting plates 480 are welded to the bracket 482 which in turn is bolted to the upper end of the vertical plate 375.

Located intermediate the plates 480 in depending relationship thereto are a pair of longitudinally spaced parallel linkages 484 and 485. Each of the linkages 484 and 485 at its upper end is mounted on a transverse shaft 486, the transverse shafts at their respective outer ends being journaled for rotation in the plates 480. The lower end portion of each of the linkages is pivotally mounted on the respective transverse shaft 488, there being a pair of lugs 489 mounted on each end portion of each shaft 488 to depend therefrom. A longitudinally extending horizontal plate 490 at each end is located between a pair of lugs 489 and is welded to said lugs. To each end portion of the horizontal plate there is bolted a short transverse plate 491, there being provided spacers 492 on the bolts 493 for vertically spacing the plate 491 from the plate 490.

The web portion of the longitudinally extending U-shaped channel beam 495 is welded to the longitudinally extending bar 494 to depend therefrom, the end portions of the bar 494 being welded to the adjacent plate 491 to depend therefrom.

The depending legs of the beam 425 are located inter-

mediate the pair of vertical guide plates 497, of the bag top holding assembly, one guide plate being welded to a horizontal plate which in turn is bolted to the mounting plate 430 and the other guide plate being welded to the horizontal plate 499. The plate 499 has elongated transverse slots formed therein through which the bolts 500 are extended for retaining the horizontal plate 499 in a transversely adjusted position relative to the mounting plate 431.

In order to move the beam 495 (also referred to as channel) both vertically and longitudinally relative to the guide plates 497, the back end of the two-way acting piston cylinder combination 502 is pivotally connected to the intermediate portion of the linkage 484 by a pivot member 503. The outer rear end of the piston rod of combination 502 is threaded into the angle plate 504, there being provided nuts 505 for retaining the piston rod in an adjusted position relative to the angle plate. The lower end of the angle plate is welded to the mounting plates 430. By mounting the piston cylinder combination in the aforementioned manner, it will, upon being properly actuated, move the linkages, for example, linkage 485, between the solid line position of FIGURE 14 and the dotted line position of the same figure. In order to permit movement of the beam in a rearward and upward direction to the dotted line position, there is provided an elongated vertically extending slot 506 in the mid-portion of the plate 375 (see FIGURE 15). A corresponding slot (not shown) is provided in plate 427.

In order to limit the movement of the beam 495 in a downward and forward direction there is provided a limit switch 507 that at its upper end is secured to the front side mounting plate 480 to depend therefrom, said limit switch having a push button 508 resiliently urged to an OFF position. Adjustable stop member 509 is mounted on the mid-portion of back linkage 485 in position to engage the push button 508 and move it to an ON position when the linkage is in a solid line position as in FIGURE 14.

Sewing machine.—Referring now to FIGURES 1, 2, 40 14 and 17, the sewing machine 26 will be briefly described. The sewing machine 26 is supported outwardly in overhanging relationship to the V-trough conveyor assembly by a bracket 515 that is bolted to a vertical plate 516, the plate 516 in turn being welded to the angle iron 35, top cross brace 41, and backside upright 30. As will become more apparent hereinafter, the sewing machine is basically the same construction as that illustrated in FIGURE 2 of the copending application of Harold K. Fox, Serial No. 16,425, now Patent No. 3,084,642, the basic sewing machine being sold under the trade name Union Special Sewing Machine by Bemis Brother Bag Co. and therefore will only be briefly described hereinafter. The sewing machine is of a type wherein each bag starts and stops the machine and automatically clips the thread 517 and a tape 518 between the bags (if there is provided a tape bound closure). The sewing machine includes a sewing head 520 and a tape folder blade assembly 521 for folding the tape over the top of the bag prior to the bag top with the folded tape thereover entering the stitching apparatus 519 of the sewing head. The bag top in moving through the stitching apparatus engages an actuator (not shown) adjacent the presser foot (not shown) of the stitching apparatus to start, automatically clip the thread and tape, and stop the machine after the tape is sewed to provide a bag top cloture.

In order to provide a tape bound sewed closure, the sewing machine 26 has a tape roll supporting member 524 (only being partially illustrated in FIGURE 2) to dispense the tape 518 as it is used. In order to properly fold the tape over the bag top walls, 526, 527 of the bag 528 (same as bag 15 except a more advanced position) prior to the bag being advanced to the stitching apparatus by the V-trough conveyor assembly, the aforemen-

tioned tape folder assembly 521 is mounted intermediate the stitching apparatus and the bag top leveler assembly. The tape folder blade assembly is secured to a support member 530 by a pair of transversely extending bolts 531 to be positioned in front of the stitching apparatus directly above the path of travel of the bag top as it is conveyed toward the stitching apparatus.

The tape folder blade assembly includes an elongated longitudinally extending folder blade support 532 having transversely extending bolts located on either side thereof for retaining collars 535 in position to guide the tape in between the folder blades 536 and 537 mounted on the support 532. The aforementioned blades are configurated to converge toward one another in a rearward direction to fold the tape in a manner to be generally U-shaped in a transverse vertical plane. Since the tape folder blade assembly is more fully described in the aforementioned Fox application, it will not be further described herein.

Drive mechanism.—The drive mechanism includes a motor 545 mounted on the front end portion of the V-trough conveyer assembly, said motor being bolted to the belt mounting member 48 (see FIGURE 17). The motor shaft of the aforementioned motor is coupled to the input shaft of the reducer 546 that is bolted to the reducer mounting member 552, which is welded to the back side upright 30. The output shaft 547 of the reducer has a chain sprocket 548 keyed thereon for driving the endless chain 553. The chain 553 in turn drives the sprocket 549 that is keyed to the short transverse shaft 550. One end of the shaft 550 is journaled for rotation in the member 551 that is bolted to the vertical plate 92 while the opposite end is journaled in structure that is not shown.

The large diameter gear 555 is mounted in intermeshing relationship with a small gear (not shown) keyed on the shaft 550 to be driven thereby. The gear 555 in turn is drivingly keyed to the transverse shaft 556 which at one end is journaled for rotation in a mounting member 557 that is bolted to the plate 92 and at the opposite end journaled for rotation in appropriate structure (not shown).

Keyed to the shaft 556 for driving the chain 560 is a chain sprocket 561 (see FIGURE 1). The lower run of the chain 560 extends forward in a downward direction, thence reversely bent around an idler sprocket (not shown) that is journaled for rotation on the lower end of the idler arm (not shown). The upper end of the idler arm is pivotally mounted in the upwardly extending bracket 563 which in turn is mounted on the back side mounting member 48. The chain after being reversely bent around the idler sprocket (not shown), thence extends around a driven sprocket that is keyed to a shaft mounting a chain sprocket for driving gears that in turn are drivingly connected to each of the shafts mounting the front pulley 47 of the V-trough conveyer assembly. The chain 560 then extends rearwardly and upwardly to the sprocket 561. By mounting the chain 560 to extend around the pivotally mounted idler sprocket, the elevation of the elevating base 45 may be varied without changing the length of the chain since the idler sprocket pivots to compensate for the variations of the elevation of the base.

Also keyed to the shaft 556 to be driven thereby is a chain sprocket (not shown) that drives the chain 566. The chain 566 drives the sprocket 567 that is keyed on one end of the transverse shaft 568, there being provided a tensioning sprocket member 569 that is bolted to the brace 36 for properly tensioning chain 566.

Shaft 568 is journaled for rotation in gear housing 573 that is mounted on the horizontal plate 580, the plate 580 being provided with elongated slot 581 through which the chain is extended (see FIGURE 2), and is mounted on the frame members 36 and 41. The shaft 568 through appropriate gears (not shown) in the gear housing 573 drives the transverse shaft 574 and the vertical shaft 578,

The shaft 574 in turn is coupled to the transverse shaft member 575 to drive the shaft 576 of the gear housing 577 mounted on the plate 582, the plate 582 being welded to the adjacent frame members 36 and 41. The shaft 576 through appropriate gears in the gear housing 577 drives the vertical shaft 579 (see FIGURE 1).

The shafts 578 and 579 are mounted in transversely spaced parallel relationship, the upper ends of said shafts being mounted in structure not shown while the lower ends are journalled for rotation in the respective horizontal plates 583 that are welded to the adjacent upright 30. Each of the shafts 578 and 579 at their lower ends have a chain sprocket 585 keyed thereto for driving the respective chain 586. Each chain 586 extends partially around the chain tensioning member 587 that includes an elongated rearwardly extending arm pivotally connected to the adjacent upright. The spring tensioning member also includes a coil spring for resiliently urging the sprocket thereof into engagement with the inner run of the chain. Each chain 586 is mounted to drive the chain sprocket 588 that is keyed to the respective pulley shaft 100 of each side belt mounting sub-assembly. Due to the provisions of the aforementioned chain tensioning members 587 the proper tension is retained on the chains even though the side belt sub-assemblies are adjusted to vary the transverse spacing therebetween. Through the aforementioned chains 566 and 586 and associated elements, the rotation of the shaft 566 drives the belts 104 of the side belt sub-assemblies at the same rate of speed that the pulley shaft 47 drives the V-trough conveyer belts 49.

In order to drive the bag top creasing assembly, a sprocket 591 is keyed to the intermediate portion of the shaft 578 (see FIGURE 17) to drive the chain 592 which in turn drives the sprocket 414 that is keyed to the upper end of the shaft 378 (see FIGURES 5 and 14). The rotation of the shaft 378 in turn drives the spur gear 413 mounted thereon to rotate in a direction of the arrow 594 (see FIGURE 13) while the aforementioned spur gear in turn drives the spur gear mounted on the shaft 399 to 40 rotate shaft 399 in the opposite direction. As a result, the inner runs of belts 412 (also belts 469 and 473 respectively) move in the same direction at the same speed as the V-trough conveyor belts.

Referring now in particular to FIGURES 2, 16 and 17, the structure for driving the swinging guide cam shaft 354 will now be set forth. A chain 594 is driven by a sprocket (not shown) keyed to the shaft 556, said chain in turn being extended around a sprocket wheel 595 mounted on a conventional single-revolution clutch 596. The clutch is mounted on the rotary shaft 597 and is of the well-known type which, when actuated, is automatically disengaged when the driven shaft 597 has completed a single revolution. For actuating the clutch 596 there is provided an operating arm 598 mounted on a rockshaft 599 that at either end is journalled for rotation in vertical plates 600 and 601, the opposite end of the operating arm operatively engaging the clutch 596. A crank arm 602 is connected to the shaft 599 and the armature 603 (see FIGURE 18) of the clutch operating solenoid 668 mounted on the housing 124.

In order to prevent the clutch overrunning after it has made a single revolution, a stop arm 606 at one end is rotatably mounted on the shaft 599 and at the opposite end has an upwardly extending projection of a size to move radially inwardly into the slot of a clutch plate 608 (mounted on the rotary shaft) to prevent the rotary shaft from rotating until the operating arm is actuated, the operating arm being provided with members 607 for moving the top arm out of the slot. A coil spring (not shown) resiliently urges the arm 606 to a position to move its projection into the clutch plate slot. When the projection is moved out of the aforementioned slot by actuation of the clutch, the rotary shaft 597 is turned through a single revolution.

Keyed to the shaft 597 to rotate therewith is a sprocket wheel 612 that drives a chain 613 extended around a sprocket 614 mounted on the shaft 615, there being provided a chain tensioner 616 mounted on the frame for properly tensioning said chain. The chain 613 extends upwardly through a slot 114a formed in the plate 114. The shaft 615 is journalled for rotation in the gear housing 617 that is mounted on the plate 114, the shaft 615 through appropriate gears (not shown) in the gear housing drives the shaft 618 which is coupled to the cam shaft 354 for rotating the last mentioned shaft.

To synchronize the movement of the carriage and the structure mounted thereon with the movement of the swinging guide assembly, a sprocket 620 is also keyed to the rotary shaft 597, there being a chain 621 extended around sprocket 620 and a sprocket 622 that is keyed to the shaft 131 for rotating shaft 131 and thereby the cam 132.

Due to the aforementioned drive connections, upon actuating the motor 554 the V-trough conveyer belts, the side belts 104, the bag top creasing belts 412 and belts 469, 473 are continuously operated; however, the cams controlling the swinging guides, the movement of the carriage and the structure mounted thereon are only operated during the time that the shaft 597 is permitted to rotate through the operation of the clutch 596. It is to be mentioned that a hand wheel (not shown) is connected to shaft 556 for turning the shaft by hand.

Controls.—The controls 28 include the electrical components and circuitry generally designated 625 and the pneumatic components and circuitry generally designated 624 (see in particular FIGURES 18 and 19). The electrical components and circuitry include a pair of main lines L-1 and L-2, there being a plurality of junctions 628, 629, 630, 631, 632, 633, 634 and 635 provided thereon. An ON-OFF switch 636 is provided in the lines L-1 intermediate the power inlet and the junction 628. Thus, when the switch 636 is in an OFF position, no power is supplied to the aforementioned junctions on said line.

On the main line L-2 there are provided a plurality of junctions, these junctions being 637, 638, 639, 640, 641, 642, 643, 645, 644, 646 and 647. Connected across junctions 633 and 641 is a light supplying photo relay 628, the photo relay having the light emitting member 629 connected thereto by line 618 and a light receiving member 631 connected to said relay by line 619.

The light receiving member 631 is located intermediate the outer run of the belt 104 and the control panel 624 mounted on the back side of the machine (see also FIGURES 1, 3 and 17). The member 631 is mounted on the depending rod 632 to be selectively adjustably positioned along the height thereof, the upper end of said rod in turn being welded to a horizontally extending rod 633. The forward end of the rod 633 is mounted for sliding longitudinal movement in lug 634, which is welded to the adjacent channel iron 37. The back end of rod 633 is pivotally connected to the lower end of the upwardly extending arm 635. The upper end of arm 635 is secured to one end portion of the transverse shaft 636 for rotation therewith, the end portions of the shaft being journalled for rotation in brackets 637 mounted on the respective channel iron 36. Secured to the opposite end portion of the shaft 636 adjacent the second bracket 637 to rotate therewith is the upper end of the arm 638, the lower end of said arm being pivotally connected to the rear end of the longitudinally extending rod 633 which has its opposite end portion slidably retained in the lug 634 secured to the front side channel iron 37. The upper end portion of the depending arm 639 is welded to the rod 633 and the lower end portion of the depending rod mounts the light emanating member 629 to be adjustably vertically positioned thereon. As may be noted in FIGURE 3, the rods 632 and 639 have intermediate portions that are bent outwardly in opposing directions to facilitate mounting the respective members 631 and 629 in position to be

closely adjacent the outer runs of the respective side belt assembly. The light emitting and light receiving members are mounted on the respective rods in position so that the beam of light is projected from the member 629 between two runs of belts 104 and the belt rollers and received by the light receiving member.

In order to selectively vary the longitudinal position of the light emitting member and light receiving member such that a bag moving therebetween will "break" the beam at a proper location and also so that the light beam will not be interrupted by the adjacent vertical rollers 86, there is provided a horizontally extending crank shaft 641 that at one end is journaled for rotation in a block 642 secured to upright 33 and mounted to preclude longitudinal movement of the shaft relative to said block (see FIGURE 4). On the crank shaft there is keyed a hand wheel 644 for rotating the crank shaft.

The opposite end portion of the crank shaft has threads that form a matching fit with the internally threaded aperture of the lug 643, the lug 643 being pivotally and slidably mounted on arm 638. By rotating the hand wheel 644, the crank shaft is rotated and thereby causes the lug 643 to move in a longitudinal direction thereon, the movement of the lug in turn causing the arms 635, 638 to pivot about the axis of the shaft 636 and the members connected to said arms to longitudinally move the light receiving member 631 and the light emitting member 629 in the same direction.

The light beam between members 629, 631 being broken results in the relay 628 moving its switch 649 to form a closed circuit between terminals 647 and 648, terminal 647 being connected via line 651 to the junction 650. Connected across junctions 650 and junction 638 is a timer 652, while a timer 653 is connected across junctions 628 and 637. The timer 653 is of a construction that after a desired delay has elapsed, it moves its switch member 654 to form a closed circuit between terminals 655 and 656. The terminal 656 is connected via line 657 to junction 629, while terminals 655 are connected via line 659 to terminal 648. As a result of providing timer 653, the timer 652 cannot be energized prior to the warm-up of the photo amplifier of relay 628 even though a bag has broken the beam of light emitted from member 629.

The timer 652 is of a construction that after being energized, it moves the switch member 657 to close the circuit between terminals 656 and 655 and retains the switch member in the closed position for a selected time interval before moving said member to an open position. Terminal 655 is connected via line 658 to junction 650. Connected across terminal 656 and junction 639 is the solenoid coil of relay 660, said relay upon being energized operates its switch member 661 to complete the circuit between terminals 662 and 663. The terminal 663 is connected via line 664 to junction 630 while the solenoid coil 668 of clutch trip solenoid 668 is connected across terminal 662 and junction 640. The clutch trip solenoid 668 is energized after the switch 661 completes the circuit between terminals 662 and 663 and thereupon causes the arm 602 to move to operate the single revolution clutch to rotate rotary shaft 597 through a single revolution. The timer 652 and relay 628 hold their respective switch members in an "ON" position for a period of time sufficient for the clutch trip solenoid to operate the clutch to initiate rotation of shaft 597.

The bag being advanced by the V-trough conveyer assembly past the feeler arm 433 rotates it in a direction of the arrow 438 to move the push button 437 and switch member connected thereto from an open position to a position to close the electric circuit between the feeler arm switch terminals 571 and 572. The switch member 437 upon completing the electric circuit through terminals 571 and 572 energizes the timer motor of the timer 672, which is connected across terminal 682 and junction 645, terminal 571 being connected via line 684 to junction 634. The timer 672 is a type that holds its switch member 680

in a closed position completing the circuit between terminals 679 and 685 for a sufficient time to energize relay 676 and allows it to move its switch members and thereupon break the circuit between terminals 679 and 685, since the normally closed contact is used on the timer 672, an electric impulse is provided to relay 676 only until the timer has timed out. This is less than one-quarter of a second. This permits relay 676, which is held through its own contact 687 and switch 587, to be de-energized by switch 587, even though switch 436 is still closed due to a bag still in contact with actuator 433. The timer 672 resets (moves member 680 to complete the circuit between terminals 679 and 685) when actuator 433 leaves contact with the bag, since the feeler arm is moved to a datum position by push button 437 after the bag has moved past said arm.

The solenoid coil of relay 676 is connected across junctions 644 and 677, junction 677 in turn being connected via line 678 to terminal 679 of the timer 672. The terminal 685 is connected via line 681 to junction 682 which in turn is connected via line 683 to terminal 572.

When the solenoid coil of the bag top leveler and holder assembly relay 676 is energized, it moves its normally closed switch member 687 to open the circuit between terminals 688 and 690 of said relay, terminal 690 being connected via line 691 to junction 692 that in turn is connected via line 693 to junction 635. The solenoid coil of the bag top leveler solenoid operated air valve 695 is connected across junction 646 and the second terminal 688 of the relay 676.

The relay 676 has a third terminal 697 and a fourth terminal 698 that has a circuit completed therebetween by the energization of the solenoid coil of said relay moving the switch member 699 to a closed position, the fourth terminal being connected via line 700 to the junction 692. The third terminal is connected via line 701 to junctions 702, the solenoid coil of the bag top holder solenoid operated air valve 703 being connected across junctions 702 and 647. The junction 702 is also connected via line 704 to the first terminal 705 of the limit switch 507, the limit switch 507 having a second terminal 706 that is connected via line 707 to junction 677. The switch member 508 of limit switch 507 is operated by the movement of the arm 485 to its lowermost position which thereupon moves the normally closed switch member 508 to open the circuit between terminals 705 and 706, and thereupon de-energizing the solenoid coil of the bag top leveler and holder relay 676 (switch 437 being opened prior to switch 680 being returned to a closed position).

The electrical circuitry having been described, the pneumatic circuitry and component 624 will now be set forth. The pneumatic component includes an air supply 712 that is connected via line 713 to junction 714 for supplying air under pressure to the one ends of the lines 715 and 716. The opposite end of line 715 is connected to the inlet port of the bag top holder solenoid operated air valve 703. The solenoid valve 703 also has a control port 718 and a port 719, the control port normally being in fluid communication with the port 719 via member 720. However, when the solenoid coil of the valve 703 is energized the member 720 moves to place the control port in fluid communication with the inlet port 717 and break fluid communication between ports 718 and 719. Port 719 is in fluid communication with the exhaust 723 via line 721 while the port 718 is in fluid communication with the port 724 of the cylinder 456 via line 725.

The air supply is also connected via line 716 to junction 729 which in turn is connected via line 730 to the first port 731 of the cam operated air valve 732. The second port 733 of the valve is connected via line 736 to port 737 on one side of the piston cylinder combination 160, while port 738 on the opposite side of said piston cylinder combination is connected via line 739 to the third port 734 of the valve 732. A fourth port 735 of said valve is connected via line 740 to junction 741.

The valve 732 is mounted on the angle iron 40 and has a plunger 742 operating internal connections that in one position place the port 735 in fluid communication with the port 733, and port 734 in fluid communication with port 731; and in a second position places port 734 in fluid communication with port 735, and the port 733 in fluid communication with port 731. The plunger is operated between the two aforementioned positions by a cam 743 mounted on the rearward end of the cam shaft 354, the plunger being provided with a cam follower 744 for bearing against the cam peripheral surface. As the cam shaft rotates, the cam first forces the plunger in an inward direction (arrow 745) to the position illustrated in FIGURE 19, and then at the time the gusset formers are to be withdrawn from the bag it permits the plunger to resiliently be moved by a spring member (not shown) in a direction opposite the arrow 745 to the second position referred to above.

The first port 751 of the solenoid operated air valve 755 for the bag top leveler piston cylinder combination 502 is connected via line 750 to the junction 729 while the second port 752 of said valve is connected via line 749 to the junction 741. A third port 753 of valve 755 is connected via line 757 to one port 759 of the piston cylinder combination 502, and a fourth port 754 is connected via line 756 to the port 758 on the opposite end of the piston cylinder combination. The valve 755 is of a construction that in a first position the port 751 is placed in fluid communication with port 753, and port 752 is in fluid communication with the port 754; and in a second position the port 753 is in fluid communication with the port 752 and the port 754 is in fluid communication with port 751. The operation of the internal connecting members of the valve between the two aforementioned positions is controlled by the solenoid coil 695, the port 759 being connected through ports 751 and 753 and appropriate lines to the air supply when the solenoid coil of valve 695 is energized (first position).

The main drive motor 545 has a motor starter circuit connected across junction 643 and 758, there being a running lamp 759 connected across junction 758 and junction 642. The junction 758 is connected via line 760 to the junction 761. A switch 762 is connected across junctions 761 and 631, switch 762 being a conventional ON-OFF switch that remains in the position in which it is set. A jog switch 763 is connected across junction 761 and 632 in parallel with the switch 762 and is of the type that is resiliently urged to an OFF position, but completes the circuit between junctions 632 and 761 when held in an ON position.

The sewing machine motor 765 and its actuator switch (not shown) are also connected across lines L-1 and L-2, the switch being of a type to actuate the motor when it has been contacted by the bag and to de-actuate the motor upon the bag top closure having been completely formed. The aforementioned connections and actuator switch are not shown since it is conventional sewing machine equipment.

Operation.—For purposes of describing the operation of the machine it is assumed that the elevation of the V-trough assembly has been adjusted so that the stitching apparatus of the sewing machine will sew the bag top closure at the desired height for the run of bags being sewed and that the side belt assemblies 31 and 30 have been transversely adjusted so that the inner runs of the belts 104 firmly engage the side walls of the bag therebetween. The description of making the aforementioned adjustments of the elevation of the V-trough assembly and the transverse adjustments of the side belt assembly will not be set forth since it is believed that the manner of making said adjustments is apparent from description of the structure of the aforementioned assemblies.

The apparatus of this invention is started up by first closing the main line switch 636 and switch 762 to thereby actuate the motor 545. Upon the motor being actu-

ated, it, through structure described heretofore, continuously rotates the shaft 556, said shaft in turn through appropriate sprockets, chains and shafts drives the upper runs of the V-trough belts, the adjacent inner runs of the side belts 104, the inner runs of bag top creasing belts 412 and the inner runs of the bag top holding belts 459-473 to move forwardly in a longitudinal direction of the arrow 118 at the same rate of speed. Assuming at the time that the motor is actuated, the gusset forming assembly, the swinging guide assembly, the bag top leveling assembly and sewing machine components are in a datum position, they remain in said position until the clutch solenoid 668 is energized to rotate the clutch arm 602 and thereby the rocker shaft 599 and rocker arm 598 to operate the clutch 596 to rotate the shaft 597.

After the motor 545 has been started, assuming that the type of bag scale and filling machine being used is the one illustrated in FIGURE 1, the operator positions an empty bag on the spout and operates a switch there-of (not shown) to initiate the cycle of operation of the machine 11. The machine 11 clamps the bag to its hopper spout and discharges a weighed charge into the bag and then the clamps releasing the bag to drop onto the rearward end of the V-trough conveyer assembly upon said bag being filled with the weighed charge. If the bag scale and filling machine is of the nature described in the Helm et al. application, then the operations of picking up, opening, positioning and clamping the bag are automatic.

Upon the filled bag being dropped onto the V-trough conveyer assembly, the belts 49 move it in a longitudinally forward direction (arrow 118) so that the bag enters between the throat portion 105 of the side belt conveyor assembly. The bag is continuously advanced by the belts 49 and 104 to a point that the leading edge 15a of the bag interrupts the beam of light emitting from member 649 whereupon relay 628 moves switch member 649 to close the circuit between contacts 648 and 647 to thereby energize the timer 652, it being assumed that the timer 653 has completed the circuit between terminals 655 and 656. Energization of the timer 652 results in it moving the switch member 657 to complete a circuit that energizes the solenoid coil of the relay 660, timer 652 being set for a time cycle to permit the clutch solenoid coil operating the rocker arm 602 and thereby actuate the clutch 596 to cause the shaft 597 to be rotated in a single revolution.

At the time the rotary shaft 597 starts to rotate, the carriage is in a datum position which is its position that longitudinally is most closely adjacent cross brace 32, i.e. position of FIGURE 4. The rotation of the rotary shaft results in the carriage cam 132 being rotated to pivot the arm 122 about the axis of shaft 123 in a direction of the arrow 128 to move the carriage in the direction of the arrow 118, the cam track 132a being configurated such that the carriage is moved in a forward longitudinal direction at the same rate of travel as a bag on the V-trough conveyer assembly. At the same time that the carriage is moved in a forward direction the rotation of the rotary shaft 597 through structure described heretofore results in the cam shaft 354 and the cam 743 thereon to be rotated, the outer periphery of the cam 743 being configurated such that the plunger 742 is moved to the second position (after the shaft 743 has rotated only a few degrees) to place port 731 in fluid communication with the cylinder port 737. This results in the piston rod moving the arm 156 about the axis of the shaft 196 in a direction of the arrow 780 to thereby move the bars 141 and the structure thereon downwardly and rearwardly relative to shaft 146. However, due to the parallel linkage connections, the bars 141 are retained in a horizontally extending position as they are moved relative shaft 146.

While the gusset former sub-assembly is being moved downwardly and rearwardly through the actuation of piston cylinder combination 160, no movement of the gusset formers relative to the bars 141 takes place since the length of linkages 231, 233, 273, 284 and the configurations of the cams 260, 246 are chosen to preclude movement thereof. That is, as the gusset former sub-assembly is being lowered the cam follower 268 bears against the minimum diameter portion of cam 262 and cam follower 244 bears against the maximum diameter portion of cam 246. At the same time the gusset formers are also moved in a forward direction due to the movement of the carriage. Thus the overall movement of, for example, point x on bar 141 (see FIGURE 6) is in the direction of arrow 800 from datum position R generally along the dotted line 801, it being mentioned that the actual line of movement is not a straight line since the parallel links 144 and 148 are pivotally mounted.

As the bar 141 (point x) moves in the direction of arrow 800, the aforementioned cams are rotated in the direction of the arrow 254 due to the horizontal movement of the sprocket 248 relative to the chain 249 which causes the sprocket to rotate. As the bag is moved in a forward direction, the gusset formers are retained in their relative positions illustrated in FIGURE 4 until the inside formers 168, 169, 170 and 171 are moved down into the bag mouth a distance approximately equal to the vertical edges thereof (distance H—see FIGURE 7). At this time the piston rod 157 has been fully retracted and therefore the bars 141 are no longer moved in a downward direction (now located at S—FIGURE 6). However, the cam 262 is rotated to a position relative to the cam follower such that the cam now progressively moves the follower away from the axis of rotation of the cam as point x moves in the direction of arrow 802 along line 803 away from point S. This results in the linkages which the cam follower 268 controls rotating the shaft 200 in the direction of the arrow 782 (see FIGURE 4) and the shaft 185 in the direction of arrow 783 to thereby move the lower ends of formers 167, 168 to be further longitudinally spread apart relative to the lower ends of formers 170 and 171. Due to the rotation of the shaft 185 the cam follower 194 progressively bears against the cam surface of an increasing radial distance from the shaft 185, the cam 186 being prevented from rotating with the shaft since the spur gear 184 is presently retained in a stationary position by spur gear 179. The movement of the cam follower 194 outwardly from the axis of shaft 185 causes the hub 192 to pivot about its axis in the direction of arrow 784 (see FIGURE 8) and the hub 197 to be pivoted in the opposite direction due to the provision of the slot 192c and the stud 198. The pivotal movement of the aforementioned hubs results in the inside formers 170 and 171 being moved apart in a transverse direction from the position illustrated in FIGURE 8 to the position illustrated in FIGURE 20. Since the corresponding structure is mounted on the forward end of the bars 141, the inside gusset formers 167 and 168 are likewise transversely spread. The aforementioned movement of the gusset formers 167, 168, 170 and 171 in the manner described result (simultaneously being both longitudinally and transversely spread) in the bag top opening being moved to assume the rectangular shape of FIGURE 20. Immediately thereafter, the cam follower riding on the cam surface of the cam 246 comes in contact with the cam surface of decreasing radius and thereupon the outside gusset formers 166 and 169 are caused to pivot about their respective shaft on which they are mounted so that their lower ends of said gusset formers are moved longitudinally toward one another from the positions illustrated in FIGURE 20 to a position illustrated in FIGURE 21 to thereby provide the gussets 15e and 15f as illustrated in the last mentioned figure. At this time point x has moved very

closely adjacent point T of the path of movement of said point.

The vertical guide plates mounted on the swinging arm 291, 290, 294 and 295 during the interval of time 5 in which the carriage moves from the datum position to the position in which the gussets are formed as illustrated in FIGURE 21, are in their maximum spread apart condition such as partially illustrated by the guide arms 294 and 295 in FIGURE 4. During the same period 10 of time, the cam follower 355 of a cam 356 is permitted to move radially inwardly toward the shaft 354 and as a result the vertical guides on the arms 293 and 292 are transversely moved apart. When the cycle of 15 the gusset former assembly has progressed so that the gussets are formed as illustrated in FIGURE 21, all three cam followers 355 are simultaneously moved radially outwardly from the shaft 354 due to the configurations of the respective cams to thereby through structure described heretofore cause the vertical guide plates 297 and 300 to be simultaneously moved closely adjacent to one another such as indicated in FIGURE 20. The guide plates in their adjacent position bear 20 against opposite sides of the bag top to slidably retain it in the shaped position of FIGURE 21 as the bag top moves into the bag top creasing assembly. As the bag leaves each of the three sets of guide plates, the guide plates retract in order. This prevents the next bag from hitting the guide plates. The next bag will 25 follow very close. The above method also makes high speeds possible. At this time the plunger 742 is permitted to move to a position to move the movable valve member of the valve 732 to a position to connect the ports as illustrated in FIGURE 19, due to the configuration of cam 743. This results in the port 737 being 30 connected to the air supply. Thereupon, the piston rod 35 is moved outwardly to rotate the arm 156 in a direction opposite the arrow 780 to move the gusset former sub-assembly in a vertically upwardly and forward direction relative to the carriage to withdraw the gusset 35 formers from the bag mouth (along line 805 and in 40 the direction of arrow 806 of FIGURE 6).

It is to be mentioned that in place of mounting the guide plates 297 and 300 on the horizontal arms and utilizing the guide arms, rods connected to said horizontal arms and the mechanism for moving said guide arms, a piston cylinder combination may be provided for each guide plate. The piston cylinder combination for plates 297 would have the respective cylinders 45 mounted on the back side of the frame in a fixed position for translating the piston rods thereof for moving the respective guide plate 297 connected to one end of a piston rod from the position illustrated in solid lines in FIGURE 10 to a translated retracted position (not illustrated), while the piston combination for plates 300 would likewise have their respective cylinder mounted 50 on the front side of the frame for moving the piston rods thereof to translate the respective plate 300 from the position illustrated in solid lines in FIGURE 10 to a retracted position. Appropriate controls would be provided for the piston cylinder combination to operate 55 the respective plates 297 and 300 in the same time sequence described heretofore as accomplished by the swinging guide cams.

After all the gusset formers have been completely 60 withdrawn from the bag mouth the bars 141 are at their most elevated position and in their longitudinally foremost position at point U. Further rotation of the carriage cam 132 (due to the configuration of the cam track) causes the control arm to pivot in a direction 65 opposite the arrow 128 and thereby start returning the carriage to a datum position (movement from point U to point R along the line therebetween in FIGURE 6). The carriage in being returned to its datum position causes the sprocket 248 to be rotated in a direction opposite the arrow 254 through the chain 249, and thereupon 70

time the bag 526 (illustrated in FIGURE 1) has a strip of tape 789 folded over the top edge portions of the bag, said strip being sewn to the bag by thread 788 to form the sewed tape bound bag top closure.

Since the cycle of operation of the swinging guide assembly and the gusset former assembly is independent of the operation of the bag top leveler and former assembly other than that they are operated in sequence; while the bag top lever and holding assembly is operating to carry out its function, the gusset former assembly may be operating to form gussets in the bag top of another bag. As a result of using the machine of this invention, applicants have been able to increase the speed of operation so that a high rate of bags per minute may be handled.

It is to be mentioned that the bag top leveling assembly is necessary for sewing with tape since positions of the bag top relative to the tape and stitching are somewhat critical. However, it could be omitted for sewing when the machine of this invention is used for providing a type of bag top closure that does not utilize tape.

A feature of the gusset former assembly that has not been set forth heretofore is that in the event a bag is tilted so that the leading edge is inclined in, for example, a vertically rearward direction, the lower portion of the leading edge is located in advance of a transverse vertical plane passed through the light beam prior to the intermediate portion of the leading edge breaking the light beam. As a result, the initial movement of the gusset former assembly is delayed slightly over that from which it would have been normally actuated if the bag had been in a vertical upright condition. However, once the gusset former assembly is actuated, the movement of the gusset former subassembly, including the gusset formers mounted thereon is the same as described heretofore.

With the bag inclined rearwardly the lower ends of the forward inside gusset formers 67 and 68 (prior to any longitudinal movement thereof relative to bars 14) enter the bag more closely adjacent the leading edge than if the bag were in an upright condition. This results in the inside gusset formers being moved longitudinally apart shifting the bag top in a forward direction relative to the bag bottom as the inside formers move the bag top to a rectangular plan configuration such as illustrated in FIGURE 20. The shifting of the bag top in the aforementioned manner has a straightening effect on the bag and therefore, when the bag enters the area of the bag top leveling and holding assembly the upper edges of the bag top are more nearly in the position which they are to be sewn with a tape bound closure, than they would be in the gusset former assembly did not have any straightening effect on an inclined bag. Likewise, if the bag is inclined in a forwardly direction, then the breaking of the light beam is slightly in advance of what would normally occur and as a result the back inside gusset formers prior to being moved longitudinally relative to bars 141 are more closely adjacent the trailing edge than they would be if the said gusset formers had entered the bag mouth of a bag in an upright condition. This results in straightening bags inclined in a forward direction.

In the event that lower speeds are permitted and also where tape sewing is not required the machine of this invention may be appropriately modified. For lower speeds, the gusset former assembly need not travel in a longitudinal direction with the bag. It would only have to have vertical movement. In such a case, the bag would be brought to a stop under the gusset former assembly by means of gates or stopping the conveyer. The gusset former assembly would then be lowered into the bag to form the gussets and then elevated. The gates would open or the conveyer would then be started again and move the bag in a forward direction. If the sewing operation included the provision of tape, the bag top leveling and holder assembly would be utilized; however, if the bag

top closure does not include tape, the last mentioned could be eliminated.

If the apparatus 10 is to be used for providing bag top closures on flat tube bags (without providing gussets) then the gusset former assembly would be modified to provide only two inside formers that are mounted to have their lower ends moved longitudinally relative one another and no outside formers would be provided. The drive structure of the gusset former sub-assembly would accordingly be modified. Also the machine of this invention may be modified in the manner that the bag top leveling would be accomplished with the belts, or rollers instead of the U-shaped guide channel.

As many widely apparently different embodiments of this invention may be made without departing from the spirit and scope thereof, it is to be understood that we do not limit ourselves to the specific embodiments herein.

What we claim is:

1. In apparatus for shaping and retaining in condition for a sewing operation to provide a sewed bag top closure on a sewed bag, a longitudinally extending frame, means mounted on the frame for supportingly conveying a filled bag in an upright condition in a forward direction, said conveyor means including a V-trough conveyor, a longitudinally extending conveyor subframe for mounting said conveyor, and means on the frame for selectively elevating and lowering said subframe, the last mentioned means including at least two crank arms each having one end moveably connected to the respective opposite longitudinal end portion of the subframe and means mounted on the frame for simultaneously moving the crank arms to selectively lower and elevate the subframe, means mounted on the frame for shaping the bag top of a bag on said conveyor means for a sewing operation, means mounted on the frame forwardly of the bag top shaping means for retaining the bag top in a shaped condition as said bag is conveyed forwardly by said conveyor means, said retaining means including means for leveling a bag top for a taping operation, means for driving said conveyor means, and means for automatically operating said bag top shaping means and said bag top retaining means in the aforementioned manner.

2. The apparatus of claim 1 further characterized in that the movable connection of each crank arm to the sub-frame comprising means for slidably connecting the said one ends of the crank arms to the sub-frame for longitudinal sliding movement in opposite longitudinal directions, and that the crank arm moving means includes means on the frame for simultaneously rotating each of said one ends of the crank arms about a different transverse axis in opposite directions.

3. In bag top forming apparatus for shaping a bag top preparatory to be provided with a sewed bag top closure, a longitudinally extending frame, conveyor means mounted on the frame for conveying a filled bag in a longitudinally forward direction, means mounted on the frame above said conveyor means for forming gussets in the bag as it is being conveyed in a forward direction by said conveyor means, said gusset forming means including inside gusset formers extendable into the bag mouth, outside gusset formers and means for operating said gusset formers to form gussets in the bag top while the bag is being moveably conveyed in a forward direction by said conveyor means, means for automatically leveling the formed bag top and retaining it in a leveled condition as the bag is being advanced by the conveyor means, the last mentioned means being mounted on the frame forwardly of the gusset forming means, and means for operating the conveyor means, gusset forming means and bag top leveling and retaining means in the aforementioned manner.

4. The apparatus of claim 3 further characterized in that a sewing machine is mounted on said frame in overhanging relation to the conveyor means and in advance of the bag top leveling means, said sewing machine in-

cluding means for folding tape over the bag top as the leveled bag top is being retained in a leveled condition by the bag top leveling, retaining means, means for stitching the folded tape to the bag top, and means for operating the stitching means.

5. The apparatus of claim 3 further characterized in that there is provided a swinging guide assembly mounted on the frame adjacent the gusset forming means for retaining the bag top in a shaped condition between the interval that the gussets are formed and the bag top being engaged by the bag top leveling and retaining means, and means on the frame for operating the swinging guide assembly.

6. In apparatus for providing a tape bound bag top closure on a filled bag and having a frame, a conveyor assembly on the frame for supportingly conveying the bag in a position to be provided with said closure, a bag top leveling and holding assembly comprising first means mounted on the frame above the conveyor assembly for releasable movably retaining opposite bag top walls transversely closely adjacent one another as the bag is being conveyed by said conveyor assembly, and second means mounted on the frame adjacent said first means for alternately being elevated above the top edges of a bag top wall and bearing against the bag top edges to move them to a horizontal condition at a pre-selected elevation, said first means including means for clampingly retaining the bag top walls at the pre-selected elevation as the bag top is being conveyed by the conveyor assembly and means for alternately moving said clamping means out of the clamping engaging position prior to bag top leveling means moving to a position bearing against the bag top edges and returning the clamping means to a position clampingly engaging the bag top walls while the bag top leveling means is bearing against the bag top edges at the pre-selected elevation.

7. The apparatus of claim 6 further characterized in that the bag top leveling means includes a longitudinally, horizontally extending channel beam having a web portion for bearing against the bag top edges, parallel linkage means having upper ends pivotally supported from the frame and lower ends having the channel beam pivotally connected thereto to depend therefrom; means connected to the linkage means for alternately moving said linkage means to move the channel beam web portion between an elevated position and said pre-selected elevation, and control means for operating said linkage means to lower the channel beam to the pre-selected elevation when the clamping means is out of clamping engagement with the bag top sidewalls and elevate the channel beam after the clamping means has moved to a position to clampingly retain the bag top sidewalls with the bag top edges at the pre-selected elevation.

8. The apparatus of claim 6 further characterized in that clamping means includes a first endless belt having an inner run, means on the frame for mounting said first endless belt for movement with its inner run in position to bear against one bag top side wall as the bag is being conveyed by the conveyor assembly, a second endless belt having an inner run, and means on the frame for mounting the second endless belt for movement with its inner run adjacent the opposite bag top sidewall, and that the means for moving said clamping means includes means mounted on the second belt mounting means for alternately moving the second belt inner run into a position relative to the first belt inner run to retain the bag top wall top edges at the pre-selected elevation and permitting the second belt inner run moving transversely relative to the first belt inner run to permit the elevation of the bag top being varied, said side belts inner runs being located at an elevation adjacent to and beneath the bag top leveling means in the position bearing against the bag top edges and means for operating the second belt inner run moving means in the aforementioned manner.

9. In apparatus for automatically leveling a bag top as

5

the bag is being conveyed in a given longitudinal direction that includes a frame and a conveyor assembly mounted on said frame for conveying the bag, a bag top sub-assembly for permitting the bag top being leveled to a pre-selected elevation and retaining it at said elevation as the bag is being conveyed by the conveyor assembly, said bag top sub-assembly comprising longitudinally elongated means for abutting against one transverse bag top side wall as the bag is being moved by the conveyor assembly, an endless belt having an inner run, means on the frame movably mounting said endless belt to have the inner run extend longitudinally adjacent the opposite bag top sidewall and means for alternately automatically moving the inner run of the belt transversely toward said elongated means to retain the bag top edges at a pre-selected elevation as the bag is being conveyed after the bag top has been leveled and transversely moved away from the elongated means prior to the bag top leveling operation.

10. In apparatus having a longitudinally extending frame for shaping a bag top of a filled bag as it is being conveyed in a longitudinal forward direction to a sewing operation to provide a bag top closure, a swinging guide assembly for reclaiming the bag top in the shaped condition comprising a plurality of first longitudinally spaced guide arms located on one transverse side of the frame, a plurality of second longitudinally spaced guide arms located on the opposite transverse side of the frame, means movably mounted on each of the first guide arms to abuttingly engage one bag top sidewall, means movably mounted on each of the second guide arms to abuttingly engage the opposite bag top sidewall, means mounted on the frame and connected to the first and second guide arm bag top engaging means for mounting the first and second guide arms for individual movement between a position positioning the bag top abutting means connected thereto in abutting engagement with said bag top and a position transversely spaced from said bag top and means for operating said guide arm mounting means to simultaneously move all the guide arms to position their respective bag engaging means in abutting relation with the bag top and sequentially move the longitudinally rearmost guide arms on either side to position their bag top engaging means in a spread apart condition and then move the next to longitudinally rearmost guide arms on either transverse side of the frame to position their respective bag top engaging means in a spread apart condition.

11. The apparatus of claim 10 further characterized in that each bag top engaging means includes a guide plate having a smooth vertical bag top engaging surface and a smooth horizontal flange for engaging the bag top beneath the bag top edges.

12. The apparatus of claim 10 further characterized each of the first and second guide arm mounting means includes a rod rotatably mounted on the frame having a guide arm mounted thereon for rotation therewith, and a tube concentrically positioned on said rod for rotation independently thereof for each additional guide arm and that the operating means includes means connected to the rods for simultaneously rotating them in opposite directions, means connected to each tube for each additional pair of guide arms to simultaneously rotate the respective pair of tubes in opposite directions and means for operating the last two mentioned means to move the guide arms and their respective bag top engaging means in the manner set forth heretofore.

13. A swinging guide assembly for bag top forming and sewing apparatus having a longitudinally extending frame comprising a pair of transversely spaced rods rotatably mounted on said frame, a tube rotatably mounted on each rod, a guide arm mounted on each tube and each rod to depend therefrom and rotate with the member on which it is mounted, the arms on the tubes and the arms on the rods respectively being in the same longitudinal

relationship, a generally vertical guide plate for each guide arm, means pivotally mounted on each arm for mounting the respective guide plate so that those on one transverse side of the frame to face those on the opposite side, means mounted on the frame and connected to the respective guide plate mounting means for retaining the mounting means to hold the respective guide plate in a vertical condition as the respective guide arm is rotated, first means for simultaneously rotating the rods in opposite directions, second means for simultaneously rotating the tubes in opposite directions and means for operating the first and second means to alternately position the guide plates on opposite sides of the frame in a transversely spread apart relationship and closely adjacent one another for abuttingly engaging opposite bag top side walls.

14. A gusset former assembly for bag top forming and sewing apparatus having a longitudinally extending frame and a conveyer assembly on the frame for conveying a filled bag in an upright condition in a longitudinally forward direction comprising a carriage mounted on said frame above said conveyer assembly for movement between a datum position and a longitudinally forward position, means on the frame for alternately moving said carriage between said positions, means mounted on said carriage for movement therewith and relative thereto for shaping the bag top of the bag on said conveyer assembly to provide gussets on the bag and control means for operating said conveyor moving means and bag top shaping means to form gussets in the bag as it is being moved by said conveyor assembly.

15. A gusset former assembly for bag top forming and sewing apparatus having a longitudinally extending frame and a conveyer assembly on said frame for conveying a filled bag in an upright condition in a longitudinally forward direction comprising a carriage mounted on said frame for movement between a datum position and a longitudinally forward position, means on the frame for alternately advancing and retracting said carriage between said positions and means mounted on said carriage for movement therewith for shaping the bag top of the bag on said conveyer assembly as the bag is being moved by said conveyer assembly, the last mentioned means including a gusset former sub-assembly and means on the carriage for alternately lowering said sub-assembly and elevating said sub-assembly above the bag top, said sub-assembly including first means extendable into the bag mouth for fully opening said bag mouth and thence permitting the bag top to be at least partially closed and second means cooperating with the first means for forming gussets in the bag top as the bag top is at least partially closed, means secured to the sub-assembly lowering and elevating means for mounting said first and second means for movement in the aforementioned manner, and third means connected to the first and second means mounting means to operate said mounting means to move the first and second means to form gussets in the bag top.

16. In apparatus having a frame and a conveyer assembly on said frame for conveying a filled bag in an upright condition through bag shaping and sewing operation, the combination of a gusset former sub-assembly comprising a pair of transversely spaced longitudinally extending mounting members, four longitudinally spaced, transverse shafts rotatably mounted on said mounting members, a depending outside gusset former mounted on each of the two outermost shafts for rotation with the respective shafts, four inside gusset formers, means on each of the other two shafts for dependingly mounting two of the inside gusset formers for rotation therewith and for movement between a transverse spread apart position with one transversely on either side of the adjacent outside gusset former and a position closely adjacent the adjacent outside gusset former, the last mentioned means including means for varying the transverse spacing of two adjacent inside formers and means

75

mounted on the shafts for operating the transverse spacing means, and means on the frame and connected to said shafts to rotate them for varying the longitudinal and transverse spacing between each adjacent set of inside and outside gusset formers to first more fully open the bag top mouth and thence form gussets in the bag top.

17. The apparatus of claim 16 further characterized in that the mounting members each include a longitudinal bar and means selectively longitudinally positionable on said bars for mounting the two shafts of an adjacent set of inside and outside formers for longitudinal movement relative the other two shafts and means connected to said bars and the last mentioned shaft mounting means for selectively varying the longitudinal position of said last mentioned shaft mounting means on said bars.

18. In apparatus for providing a sewed bag top closure on a filled bag comprising of a longitudinally extending frame, means mounted on the frame for supportingly conveying a filled bag in an upright condition in a forward direction means mounted on the frame for forming gussets on the bag top of the bag on said conveyer means, said gusset forming means including a carriage mounted on the frame for movement between a datum position and a longitudinal forward position, a gusset former sub-assembly, means mounted on the carriage for moving said sub-assembly between a lowered position and an elevated position, said sub-assembly including means extendable into the bag top mouth for shaping said bag top prior to a sewing operation, and means for operating said bag mouth shaping means to shape the bag mouth, means on the frame for moving said carriage between said positions, means on the carriage for operating the sub-assembly moving means to lower said bag top shaping means into the bag mouth and after shaping the bag mouth elevating said bag top shaping means, means on the frame for retaining the bag mouth in the shaped condition and means for driving the conveyer means, the carriage moving means, the sub-assembly moving means, the bag mouth shaping means and the bag top retaining means.

19. The apparatus of claim 18 further characterized in that the drive means includes means for continuously driving said conveyer means, means for cyclically operating the carriage moving means for moving the carriage between said carriage positions in timed relation to the movement of a bag by said conveyer means, means driven by the movement of the carriage for operating said bag mouth shaping means, means for operating said sub-assembly moving means, means for forming a driving connection to the conveyer driving means to actuate the carriage operating means and the sub-assembly operating means, and alternately breaking said driving connection and control means actuated by the movement of a bag to a given position to operate the drive connection means to form a driving connection with the conveyer drive means.

20. The apparatus of claim 19 further characterized in that the control means includes photo relay means for sensing the movement of the bag to said given position.

21. The apparatus of claim 20 further characterized in that the photorelay means includes a light emitting member, a light receiving member, means moveably mounted on the frame for selectively longitudinally positioning the light emitting and receiving members and means on the frame for selectively moving the light emitting and receiving members mounting means.

22. The apparatus of claim 21 further characterized in that the bag top shaping and retaining means include means on the frame for alternately being moved to an elevated position and a lower bag top leveling position, means on the frame for alternately being moved between a transverse spread apart position and a position retaining the bag top at the pre-selected elevation as it is being conveyed in a forward direction, means for mov-

means and swinging guide assembly in the aforesaid manner, said swinging guide assembly including a plurality of longitudinally spaced guide arms on either transverse side of the bag top and means mounted on each guide arm for abutting and engaging a bag top wall in a manner to permit slidable movement of the bag top relative thereto, said operating means including means for operating the gusset former mounting means to move the gusset formers to form gussets and means connected to the guide arms for moving the respective guide arms in the direction to transversely spread the bag top engaging means located on opposite transverse sides of the bag top prior to the formation of the gussets and moving the respective guide arms to position the bag top engaging means to abuttingly engage the bag top after the gussets have been formed to retain the bag top walls in the thus shaped condition.

28. A gusset former assembly for bag top forming and sewing apparatus having a longitudinally extending frame and a conveyor assembly on said frame for conveying a filled bag in an upright condition in a longitudinally forward direction comprising a carriage mounted on said frame for movement between a datum position and a longitudinally forward position, means on the frame for alternately advancing and retracting said carriage between said positions, and means mounted on said carriage for movement therewith for shaping the bag top of a bag on said conveyor assembly, the last mentioned means including a gusset former subassembly and means on the carriage for alternately lowering said subassembly and elevating said subassembly above the bag top, said subassembly including first means extendable into the bag mouth for holding open said bag mouth and thence permitting the bag top to be at least partially closed, said first means including four inside gusset formers, two of the inside formers being longitudinally spaced from the other two and transversely spaced from one another, second means cooperating with the first means for forming gussets in the bag top as the bag top is being at least partially closed, said second means including two longitudinally spaced outside formers located in a datum position to have the inside formers longitudinally therebetween, means secured to the subassembly lowering and elevating means for mounting said first and second means for movement in the aforementioned manner, and third means connected to the first and second mounting means to operate said first and second mounting means to move the first means and second means from the datum position to form gussets in the bag top, said first and second mounting means including means connected to the third means for mounting the inside and outside formers in the aforementioned relationship and each of the adjacent sets of inside formers and outside formers for movement between a datum longitudinally spread apart position and a together position with the opposite former intermediate the inside formers and means cooperating with the inside and outside former mounting means to operate the formers in the aforementioned manner including longitudinally spreading the pairs of inside formers as a gusset is being formed in the bag upon the operation of the third means.

29. In apparatus for shaping and retaining in condition for a sewing operation to provide a filled bag top closure on a filled bag, a longitudinally extending frame, means mounted on the frame for supportingly conveying a bag in an upright condition in a forward direction, means mounted on the frame for shaping the bag top of a bag on said conveyor means for a sewing operation, said shaping means including a carriage mounted for longitudinal forward movement on said frame between a datum position and a position forwardly of said datum position, a gusset former subassembly for forming gussets in said bag top and having a portion extendable into the bag mouth, and means mounting said subassembly on the carriage for movement both with the carriage and

relative to the carriage between an elevated position above the bag top and a lowered position with at least said portion of said subassembly extending into the bag top mouth, means mounted on the frame forwardly of the bag shaping means for retaining the bag top in the shaped condition while said bag is conveyed forwardly by said conveyor means, said retaining means including means for leveling the bag top for a sewing operation, means for driving said conveyor means, and means for automatically operating said bag top shaping means and said bag top retaining means in the aforementioned manner, said operating means including means for moving the carriage between its datum position and forward position and means for operating said gusset former subassembly elevating and lowering means to first lower said subassembly, thence form gussets in the bag top, and subsequently elevate said subassembly.

30. In apparatus for shaping and retaining in condition for a sewing operation to provide a sewed bag top closure on a filled bag, a longitudinally extending frame, means mounted on the frame for supportingly conveying a filled bag in an upright condition in a forward direction, means mounted on the frame for shaping the bag top of a bag on the conveyor means for a sewing operation, said shaping means including a gusset former subassembly for forming gussets in said bag top, said gusset former subassembly including two pairs of inside gusset formers, the inside formers of each pair being transversely, a pair of outside gusset formers, and means mounting said gusset formers for movement between a datum position and a position completely forming the gussets, the last mentioned means including means moveably mounting the outside formers in longitudinal spaced relationship for longitudinally moving the lower ends thereof toward and away from one another, means mounting each pair of inside formers in longitudinally spaced relationship and transversely on either side of the adjacent outside former for moving the lower ends of the respective inside pair longitudinally toward and away from one another to be located on either transverse side of the adjacent outside former in the completed gusset forming position, means on the frame mounting said subassembly for vertical movement relative to the conveyor means between an elevated position above the bag top of a filled bag and a lowered position that at least a portion of said inside gusset formers extend into the bag mouth thence operating said gusset former mounting means to move said inside and outside gusset formers to form the gussets and subsequently elevate the gusset former subassembly, means mounted on the frame forwardly of a gusset former subassembly for retaining the bag top in a shaped condition as the bag is carried forwardly by said conveyor means and means for operating the bag top retaining means.

31. In apparatus for shaping and retaining in condition for a sewing operation to provide a sewed bag top closure on a filled bag, longitudinally extending frame, means mounted on the frame for supportingly conveying a filled bag in an upright condition in a forward direction, means mounted on the frame for shaping the bag top of the bag on said conveyor preparatory to a bag top closure forming operation, means mounted on the frame forwardly of the bag top shaping means for retaining the bag top in a shaped condition as the bag is conveyed forwardly by said conveyor means, said retaining means including means for leveling the bag top preparatory to the formation of a bag top closure, a pair of endless side belts each having an inner run, and means on the frame mounting said side belts for movement to have the inner runs adjacent one another and traveling in a longitudinally forward direction, the last mentioned means including means mounting the inner run of one belt for transverse movement between a spread apart condition and a datum position to grippingly engage the bag top side walls between said belts and means for automatically operating 75 the transverse mounting means to relatively move the

inner runs apart while the bag top leveling means levels the bag top and moves them together after the bag top has been leveled, means for driving said conveyor means, means for automatically operating said bag top shaping means, and means for operating the bag top leveling means in the aforementioned manner.

32. In apparatus for automatically leveling a bag top as a bag is being conveyed in a given longitudinal direction that includes a frame and a conveyor assembly mounted on said frame for conveying a bag in an upright condition, a bag top subassembly for permitting the bag top being leveled to a preselected elevation and retaining it at said elevation as the bag is being conveyed by the conveyor assembly, said bag top subassembly comprising means for sequentially conveyingly grippingly engaging opposite bag top walls as the bag is being conveyed in a forward direction, transversely releasing the grip engagement therewith for an interval of time, and thence again grippingly engaging the bag top walls, longitudinally elongated channel means for bearing against the top edges of the bag top walls of the bag top being conveyed through said bag top gripping engaging means, means for alternately lowering said channel means to bear against the bag wall top edges to force them to a preselected elevation when the bag top gripping means is in a non-gripping position and moving out of a bag top wall edge engaging position after the gripping engaging position after the gripping engaging means has again returned to the bag top wall gripping position, and means for operating the bag top wall gripping means and bag top leveling means in the aforementioned manner so that said gripping engaging means transversely moves away from the bag top walls prior to the bag top leveling operation and thence retains the bag top edges at said preselected elevation as the bag top is being conveyed.

33. In apparatus for forming gussets in a bag top and straightening a tilted bag as it is being conveyed to a sew-

ing operation for providing a bag top closure, a longitudinally extending frame, a conveyor assembly mounted on said frame for supportingly conveying a filled bag in a generally upright condition in a forward direction, means mounted on the frame for shaping the bag top of a filled bag to form gussets therein and while forming gussets at least partially straighten said bag in the event it is tilted from an upright condition as the bag is being moved in a forward direction by said conveyor assembly, means for operating the bag top shaping means, and control means on the frame for sensing the passage of the central leading edge portion of a bag and actuating said operating means in timed relationship to operate the bag top shaping means to straighten a bag in the event it is tilted.

34. The apparatus of claim 33 further characterized in that said shaping means includes a plurality of inside and outside gusset formers and means mounting said gusset formers for longitudinal movement at about the same rate as the bag, vertical movement so that the inside formers will move into the mouth of the bag and movement relative to one another to form gussets in the bag top, and means for operating gusset former mounting means to move the gusset formers in the aforementioned manner.

35. The apparatus of claim 33 further characterized in that the control means include photo relay means for sensing the movement of the bag to a given position, said photo relay means including a light emitting member and a light receiving member.

UNITED STATES PATENT OFFICE
CERTIFICATE OF CORRECTION

Patent No. 3,167,897

February 2, 1965

Frank L. Hopkins et al.

It is hereby certified that error appears in the above numbered patent requiring correction and that the said Letters Patent should read as corrected below.

Column 4, line 13, for "position" read -- positioned --; lines 45 and 46, for "swining" read -- swinging --; column 18, lines 35 and 36, for "intermeshnig" read -- intermeshing --; column 23, line 60, for "assume" read -- assumed --; column 24 line 50, for "cariage" read -- carriage --; column 30, line 26 for "selectviely" read -- selectively --; column 38, line 28, after "transversely" insert -- spaced --.

Signed and sealed this 28th day of September 1965.
